UNITED STATES PATENT OFFICE.

HENRY W. O'NEILL, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed September 7, 1922. Serial No. 586,616.

To all whom it may concern:

Be it known that I, HENRY W. O'NEILL, a citizen of the United States, residing at Brooklyn, in the county of Kings, State of New York, have invented certain new and useful Improvements in Telephone-Exchange Systems, of which the following is a full, clear, concise, and exact description.

This invention relates to telephone systems, and more particularly to systems in which connections may be established by means of so-called machine switching equipment.

It is the general object of this invention in connection with systems of this nature, to provide an improved system whereby the various operations for establishing and supervising connections may be accomplished and carried out in an expeditious and reliable manner over any form of physical or phantom telephone circuit, including toll or long distance lines of great length which may be equipped for superposed telegraph working or with telephone repeaters, and to avoid the necessity of composite ringer equipments on such circuits.

Other objects and features of the invention will be set forth in the following description and claims, and although the present embodiment of the invention is shown and will be described in connection with telephone systems, it will be understood that features of the invention may readily be applied to advantage in other situations of signal operation or remote control.

In the handling of toll telephone traffic, it is well understood that the attention of an operator is required in order to insure a ticket record from which toll charges may be entered and collections made, relative to such use of the telephone plant. It has been found in practice that a single operator may be relied upon for such records. Therefore, in situations where machine switching equipment may be employed for local service in the areas of toll centers, the provision of equipment whereby an originating operator may complete connections without assistance from operators or other attendants at distant switching points or toll centers, will result in materially increasing the number of connections which may be handled during a given period over a toll line circuit, thereby improving the service while effecting

economies in operation as well as in the telephone plant.

For convenience in the descriptions presently to be given, toll traffic concerned more particularly with connections over "intermediate" distances and between widely separated points where service is commonly referred to as "long haul" connections will be considered, as it then will be obvious that the present system may readily be applied to the handling of any desired short-haul or local-service traffic. It will be pointed out that in general, service over intermediate distances is commonly referred to as two-number traffic under which calls may be handled by an operator usually reached by a calling party over a so-called two-number recording trunk circuit. This operator in addition to recording a call, also may serve as an outward line operator to complete, supervise and finally to dispose of a call or connection. For long haul connections, a calling subscriber usually reaches a recording operator over a trunk circuit commonly referred to as a single-ticket recording trunk. This operator writes the details of the call on a form ticket which is then forwarded by means of a vacuum tube ticket distributing system or otherwise, to reach an outward long distance line operator. In either case, it is the common practice for the toll operator to work back over a circuit commonly referred to as a toll switching trunk in taking up the line of a calling party, before proceeding to work out over a toll line for the purpose of reaching the party wanted in the area of a distant toll center, all as well understood in the art.

In carrying out the present invention, co-ordination of devices and equipment has been effected whereby a plurality of alternating currents of frequencies best suited to efficient transmission over telephone circuits may control sensitive receiving devices, through which, switching operations, supervisory signal control, and operations for the breaking down of a connection may be carried out entirely under the control of a single originating operator. Notwithstanding the fact that the sensitive receiving devices may be included with the main conductors of a circuit during talking periods, neither voice nor other similar currents may become effective to set up translations through these de-

an impulse formed of a plurality of alternating currents may traverse the line and at the inward end of the circuit, be translated through suitable receiving devices to condition switches for reception of selective or switching impulses. On the instant the inward switching devices have been so conditioned, an impulse formed of a plurality of alternating currents will be caused to revert over the line circuit and effect display of the dialing signal and also render the dialing equipment at the distant outward or controlling operator's position operative. Following this signal, the operator may proceed to dial the code or number of the distant station wanted.

This system further provides that notwithstanding the fact that a direct current loop circuit at the inward end of a toll line will be controlled by selective impulses of alternating currents originating at the distant outward end of the line, no revertive effects will take place relative to the sending of alternating current impulses from the inward to the outward end of the toll line, during the reception of such impulses of alternating currents. However, in case this same direct current loop may be controlled locally as by a trunks busy, line busy, by switchhook manipulation effects at a called station, or by effects due to switching through at successive switches, impulses of alternating currents will be sent back over the toll line to be manifested in either of the several different ways already described. It will also be pointed out that at the inward end of a circuit sensitive receiving devices which serve the various functions of conditioning the equipment for the reception of selective impulses, also serve for the translation of an impulse to break down a connection and further for the control of a line signal when the distant end of the circuit may be taken for use on a manual basis. In connection with the control of the line signal, these receiving devices also apply a so-called busy test condition to the various manual jacks in association with the toll line, cause visual busy signals to be displayed, and also establish a busy condition on the test terminals of bank contacts whereby a toll line may, except for such busy condition, be seized by an automatic switch.

The toll line equipment also provides that at various points on a switchboard a circuit may be taken for automatically controlling the completion of a connection. Associated means is also provided whereby a circuit may be taken for manual operation, while at other points on the same or adjacent switch-boards a line may be taken for use on a manual basis or may be seized for use through an automatic switch. Switching devices are also provided whereby these different respective points for the taking of a

toll line may automatically be disconnected one from another with respect to the main or talking conductors of a line circuit, in a manner to exclude all points of access except such point as may at any time, have right of way through precedence of seizure.

In order to effect the breaking down of an automatically established connection, the releasing of the circuit by an originating operator results in an inverse response of the switching devices already referred to whereby an impulse formed of a plurality of alternating currents is impressed over the line circuit when the line is taken, such inverse response of the devices effect application of an impulse formed of a plurality of alternating currents, to the line circuit in affecting the receiving devices already described, whereby the equipment at the distant end of the circuit will be restored automatically to its normal condition.

This invention is illustrated diagrammatically in the accompanying drawings, and by positioning the several sheets from left to right in the order of the numbering of the Figs. 1 to 4, there will be presented a complete arrangement for the handling of telephone traffic in accordance with the features of this system.

Fig. 1 shows equipment in association with a first toll center including a subscriber's station A, an operator's cord circuit C, equipment T associated with a toll line circuit L. At the point E, equipment similar to the equipment E² (Fig. 2) may be present.

Fig. 2 shows equipment which may be located at a second toll center and comprises devices T¹, which may be in duplicate of the equipment T shown in Fig. 1, equipment E² for inward or outward working on the line L, and devices R for associating the equipment E² directly with a selector switch such as S (Fig. 3). In Fig. 2^A, there is shown a primary line switch PL and a secondary line switch SL which may be used in substitution of the devices R of Fig. 2, in joining the equipment E² of the toll line L with a first selector switch as the switch S already mentioned. The devices indicated by the reference character MS within the dotted rectangle shown in the lower portion of Fig. 2^A of the drawings, represent such portions of conventional master switches in association with the primary and secondary line switch PL and SL as may be necessary to an understanding of the associated circuits. In Fig. 2^B is shown an alternate arrangement of a plurality of relays relative to reception and translation of impulses formed of alternating currents.

In Fig. 3, is shown a selector switch S joined to a trunk circuit L¹ connectively accessible to a repeater equipment TS from which a trunk circuit L² extends, while in

Fig. 4 a selector switch S^2 which serves for terminating the trunk circuit L^2 has access to a connector switch K which may engage equipment to reach a subscriber's station B .

- 5 In a further and more detailed description of the present system, operations for extending a connection from the station A (Fig. 1), to the station B (Fig. 4), on the basis that machine switching equipment is
10 provided in the respective exchange areas in which the lines of these stations terminate, will now be considered. To this end, let it first be assumed that a ticket covering such a call originating at the station A , has
15 reached an outward line operator at a toll position having access to the cord circuit C and the associated equipment. In order to insure that the calling party may readily be available when the called station may have
20 been reached, the toll operator inserts a plug 2 of the cord circuit C into a jack 1, then operates a combined splitting and dialing key 64 which may be of locking type, thereby disconnecting the right-hand portion of
25 the cord circuit and connecting a relay 50 which responds over an obvious local circuit to connect a dialing device D with the left-hand end of the cord circuit now joined with the jack 1. This jack may be assumed
30 as terminating a toll switching trunk circuit of common battery, automatic type, and that direct current from a source (not shown) on this trunk circuit may now be established through the pulsing contacts
35 of the dial D by way of an obvious circuit through the alternate contacts of the relay 50 and the main contacts of the key 64. As well understood in the art, it will be clear that the operation of the dial D may result
40 in equipment, which may be assumed as present at the point AE on the trunk circuit, functioning to establish the desired connection with the station A . During these operations the off-normal contacts 89 of the
45 dial, are rendered ineffective, principally due to a second dialing key 44 being in its normal position, thereby disassociating grounded battery relative to control of a relay 15 and a signal 11 which serve in association
50 with dialing operations when carried out over the toll line L , as presently will be described.

On completion of the dialing operations, the key 64 may be restored thereby permitting direct current from the trunk circuit to traverse the main conductors of the cord in closing circuit over a bridge path thereon which may be traced through the winding of a first alternating current relay 80, the right-hand winding of a supervisory control relay 77, and the winding of a second alternating current relay 81. While direct current through this circuit may be ineffective in the alternating current relays 80 and 81, the relay 77 may, however, respond and apply

ground potential through a resistance 29, the normal contacts of a marginal relay 35, a supervisory signal 87, thence to grounded battery through the contacts 85 of a talking key 19. It will be pointed out that on the present connection, the marginal relay 35 continues inert due to the comparatively high resistance of the sleeve circuit at the toll switching trunk jack 1. Therefore, the signal 87 may continue energized so long as direct current may flow from the trunk circuit over the bridge path already traced. It may be assumed in the present connection, that the trunk circuit is of any well known type of common battery circuit in which battery current will be present on the main conductors of the trunk so long as the receiver may be on its switchhook at a connected station, as the station A , while removal of the receiver from its switchhook will result in disconnection of the direct current from the trunk circuit. It will therefore be readily understood that the relay 77 under control of direct current through its right-hand winding, may affect the signal 87 in unison with operations of the switchhook at the station A .

During the present connection, the left-hand locking winding of the relay 77 will be idle, this winding being effective only in situations where the plug 2 may be inserted in the jack of a trunk or toll line circuit, usually of the ring-down type, on which the resistance of the sleeve circuit may be low as compared with the resistance of the sleeve circuit of a toll switching trunk, thereby permitting flow of sufficient current through the relay 35 to effect its operation. Such a connection will be described further on.

Proceeding with the present assumed connection, the operator may actuate the second combined dialing and splitting key 44 to isolate the left-hand portion of the cord circuit C in associating the dial D and associated equipment with a plug 3 which now may be inserted in a jack 4 of the toll line L . This permits a local circuit to be traced from grounded battery, through the normal contacts 85 of the talking key 19, the left-hand normal contacts of a relay 58, the lowermost normal contacts of a ringing key 55, by way of the parallel connected local contacts of the two alternating current relays 80 and 81, the armature and lowermost contact stop of a polar relay 9, winding 13 of this relay, the winding of marginal relay 58, the sleeve of plug 3 and jack 4, normal contacts 27 of a relay 22 and the winding of a relay 10 to ground. The left-hand contacts of the relay 58 which responds at this time substitute grounded battery at this relay for the grounded battery at the key 19. The response of the relay 10 effects at its uppermost contacts, switching of the con-

ductors of the toll line L from the equipment E to receive alternating currents at 700 and 1100 cycles per second from the sources 20 and 21 respectively, by way of the uppermost normal contacts of the relay 22. Closure of the lower-most contacts of the relay 10 connects the winding of the relay 22 in parallel with the winding of the relay 10. The actuation of the relay 22 switches the line L from the sources of alternating current 20 and 21 to the tip and ring conductors of the jack 4. A further circuit may now be traced from grounded battery, through contacts 60 of a relay 62, resistance 61, contacts 28 of the relay 22 to ground through the winding of the relay 10. When the relay 22 has fully operated, its contacts 27 and 28 will have substituted the circuit last traced through the contacts of the relay 62 for the sleeve circuit of the connection in retaining the relay 10 energized, while the lowermost contacts of the relay 10 maintain relay 22 under control of the sleeve circuit. The inner transfer contacts of the relay 22 disconnect a lead 63 and apply ground to a lead 43 relative to a busy lead 53 in associated equipment which may be assumed as present but not shown, at the point E . This will be rendered clear in connection with description of duplicate equipment E^2 of Fig. 2, in which the leads 243, 253 and 263 respectively correspond with the leads 43, 53 and 63.

The relay 10 is of a quick-to-operate but slow-to-release type, while the relay 22 is of a slow-to-operate but quick-to-release type. Therefore, the difference in time of operation of the two relays may represent an interval during which the alternating currents may be included with the toll line circuit. The difference in time of response in either direction of these relays is further augmented due to the fact that the relay 22 may respond and release only by way of contacts of the relay 10, and in addition to this, the current resistance drop in potential on the windings of the relays 22 and 10 during the time they may be in parallel, one with the other, in receiving current over the sleeve path of the connection as routed through the relay 9 and the relay 58 further insures sluggishness in the initial or starting movement of the relay 22 when energized. Further features relative to inverse or releasing movement of the relays whereby an impulse of current from the same current sources 20 and 21 will be applied to the line circuit L when the connection is taken down, is also brought about by the interconnective relation of the relays 22 and 10, as will appear further on in this description.

It will be obvious that the impulse of alternating currents just described as applied to the line L when this circuit was taken, will be effective in loop or metallic

relation over the conductors of the toll line at the inward end of which (Fig. 2) the circuit extends through the uppermost sets of normal contacts of a relay 215, the lowermost sets of normal contacts of a relay 220, thence over the sets of normal contacts of a relay 225 to energize two alternating current relays 230 and 240 connected in bridge on the extension conductors of the line circuit L . While these alternating current relays may be of any suitable type, they preferably may be of the mechanically tuned type shown in my copending application, Serial No. 526,152, filed December 31, 1921. As indicated in the drawing, the relays 230 and 240 may respond respectively to alternating currents at 1100 and 700 cycles per second, whereupon their normally closed contacts will be caused to separate. Therefore, arrival of the present assumed impulse of alternating currents will disable a circuit which may be traced from grounded battery, through the winding of a slow-to-release relay 250 (at R , Fig. 2), normal contacts of relay 255, whence the circuit divides, one path extending to ground through the contacts of the relay 240 while the other path includes the contacts of the relay 230 and the left-hand winding of a line signal relay 260 to ground.

As shown in the drawing, the relay 250 is normally energized, the duration or length of the present incoming impulse of alternating currents is sufficient, however, to permit this relay to release and connect grounded battery current over an obvious circuit to the uppermost winding of the relay 255. The response of the relay 255 switches the relay 250 to a release conductor 263, and places a pulsing relay 270 under control of the alternating current relays 230 and 240. Cessation of the incoming impulse of alternating currents, due to operation of the distant relay 22, as described, results in the restoring of the relays 230 and 240, thereby applying ground potential over an obvious circuit to effect operation of the relay 270. Closure of the right-hand contacts of this relay places a relay 280 in bridge on the main conductors of a trunk circuit L^1 , joined through "blocking" condensers 245 over the extension conductors already traced to the line L . The opposite end of this trunk circuit extends to a first selector switch S (Fig. 3) where it is routed through the uppermost normal contact pairs of a switching relay 310, from whence one conductor extends through the right-hand winding of a pulsing relay 300 to grounded battery, while the other conductor extends through the left-hand winding of the latter relay to ground at the normal right-hand contacts of a release relay 303. At this time, the response of the relay 280 is an idle operation (the purpose of this relay will be

- described later on), while the response of the relay 300 closes an obvious circuit to cause the operation of the slow-to-release relay 303. At the right-hand contacts of the latter relay, the ground side of the trunk circuit L^1 is switched through the lowermost normal contacts of an off-normal switch P.O.N. and the secondary windings of transformers 324 to ground at that point.
- 10 Sources of alternating currents 388 and 398 having periods of 700 and 900 cycles per second, respectively, as indicated in the drawing, may energize the transformers during periods corresponding with responses of a relay 335 as controlled by an interrupter 338. Resulting impulses of these alternating currents traverse the trunk circuit L^1 , thence over the toll line L to result in the energization of the distant 20 dialing signal 41, as presently will appear. In its operated position, the left-hand contacts of the relay 303 apply ground potential to the lead 263, thereby connecting grounded battery through the lowermost winding of 25 the relay 255 to retain this relay operated. A relay 275 responds to current from grounded battery, through its right-hand winding, thence by way of the right-hand normal contacts of a relay 222, which corresponds to the relay 22 in Fig. 1, to the conductor 263. The relay 250 also responds over an obvious circuit, to the ground potential on the conductor 263, thereby disconnecting the circuit through the uppermost winding of the relay 255 which will now be retained by the current through its lowermost winding. At the right-hand contacts of the relay 275, a line signal 267 is disconnected, while grounded battery 30 through the uppermost normal contacts of the relay 220 is applied to a conductor 253, in energizing a busy signal 254, and through condensers 288, 281 and 282 to effect a so-called click busy test condition on the sleeves 35 of the jacks 200, 251 and 299 respectively. At the left-hand contacts of the relay 275 a private or test segment 226 of bank contacts B^1 is switched from the relay 220 to ground potential, thereby establishing a busy condition 40 for the bank contacts, while ground is also connected to form a shunt path on the left-hand winding of the relay 260, in order that a zero resistance ground connection may be present for the local contacts of the relay 230 as normally present through the local contacts of the relay 240, during the reception of selective impulses as will presently be described. It will be understood that between the busy signal 254 and the ground 45 connection, other similar busy signals, as may be required in association with the various jacks each one of which may represent a single jack or respectively associated multiples may be connected. As well understood in the art, the busy conditions just

described serve to prevent the toll line L from being taken up at any one of the manual jacks or at the automatic or multiple bank B^1 during the time that the line circuit may be retained by the distant operator. 70 It will be pointed out that although the current at 700 cycles per second already described as impressed on the main conductors at the selector S, may effect responses of the relay 240, no effect will thereby be set up at this point since the pulsing relay 270 will continue energized through the local contacts of the 1100 cycle relay 230, which continues inert. 75

At the cord circuit C, the operated position of the key 44 connects grounded battery through a resistance unit 86, the local contacts of an alternating current relay 40, the normal contacts of a relay 48, and the upper normal contacts of the relay 15 to ground, while a second path from the same battery extends through the winding of a relay 42 and the normal contacts just mentioned of the relay 15 to ground. Energization of the relay 42 disconnects the sources 80 of alternating currents 69 and 79 from the cord circuit and establishes the winding of the alternating current relay 40 by way of the main make contacts of the key 44, in bridge of the right-hand end of the cord 85 circuit. It will be noted that the contacts of the relay 40 normally shunt the relay 48 which therefore continues inert, while the normal contacts of the latter relay, in turn, shunt the signal 41. 90

At the dial D, it will be noted that the pulsing contacts 5 are normally shunted by the ground connection already traced through the contacts of the relay 15. Therefore, in case the dial may be moved while the relay 48 may be deenergized, the off-normal contacts 89 of the dial will apply grounded battery from the key 44 to energize an alarm or warning signal 11 connected to ground through the lower normal contacts of the relay 15, while the shunt path on the dial contacts 5 render this device ineffective to establish impulses of current with the toll line L . 105

Assuming now that incoming alternating currents from the selector switch S arrive and complete a circuit through the relay 40, its contacts 45 will separate, thereby removing the shunt from the winding of the relay 48 which may then respond and disconnect the contacts of the relay 40 thereby rendering these members incapable of shunting the relay 48, so long as the latter relay may be in its operated position. During interruptions of the alternating currents as effected by the distant interrupter 338 each restoration of the relay 40 effects application of current through the dialing signal 41 which therefore will be caused to flash in unison with such interruptions of the impulses of 110 120 125 130

alternating currents. In moving the dial D in response to this signal the contacts 89 apply current from grounded battery at the key 44, through the winding of the relay 15, 5 the alternate contacts of the relay 48, upper normal contacts of relay 50, thence to ground through the pulsing contacts 5 of the dial and the lower normal contacts of the relay 50. The response of the relay 15 opens the 10 circuit of the signal 11 and the shunt path normally present on the pulsing contacts 5 of the dial. On release of the dial, each separation of its contacts 5 during its return movement, effects deenergization of the 15 relay 42 which switches the main conductors of the connection of the toll line L, from the relay 40 to the current sources 69 and 79 of 700 and 1100 cycles per second, respectively. In this manner, it will be readily 20 understood, that a series of selective impulses formed of alternating currents may be impressed over the line circuit L. The contacts 89 of the dial continue closed until the dial has returned to its normal position, 25 thereby holding relay 15 operated during the off-normal condition of the dial.

In response to the first separation of the pulsing contacts 5 of the dial at the beginning of its return motion, in addition to de- 30 energization of the relay 42, the relay 48 will be released to extinguish the signal 41 and also to reestablish the shunt path through the contacts of the relay 40 whereby the relay 48 is normally shunted. It will be clear from 35 the drawing that although the guard relay 15 initially may respond through the forward contacts of the relay 48, it may thereafter be retained through its self locking contacts until the contacts 89 may separate at the 40 moment the dial arrives at its normal position. Following such release of the relay 15 the pulsing contacts 5 will again be disabled and the warning signal 11 conditioned to respond in case the dial may be moved before 45 reception of an incoming impulse of alternating currents to effect response of the relay 48 and energization of the signal 41, as already described.

The alternating current relay 40 may be 50 of the type already mentioned as preferable for the relays 230 and 240, and may be tuned to respond to either one of the incoming alternating currents, 700 or 900 cycles per second. Either one or the other of these 55 currents may accordingly be idly present during moments the relay 40 may be under operation. The principal reason for the employment of the two currents for the reverteive impulses over the toll line is to insure joint response of the supervisory control relays 80 and 81 to actuate a signal 75, in case the key 44 may not be in its operated position, due to inadvertence or to the fact 60 that the operator's attention may be required peremptorily on another connection which

may necessitate the restoring of the key 44. Detailed description of the operations whereby the signal 75 may be controlled will be given further on.

Referring now to the arrival at the inward 70 end of the line L of the incoming impulses of alternating currents as controlled by the dial D, the alternating current relays 230 and 240 respond in unison to these impulses, thereby effecting corresponding responses 75 of the relay 270 which, in turn, effects successive interruptions of the loop circuit through the trunk L¹. At the first selector switch S, the pulse relay 300 in responding to such interruptions, successively completes 80 a circuit from grounded battery through a primary magnet 390, a slow-to-release relay 309, the contacts of the release relay 303 and the normal contacts of the pulse relay 300 (during each release of this relay) to ground 85 through the next contacts 313 of the switching relay 310. The switch S may be of a well known type in which the first response of the magnet 390 will effect transfer of the off-normal switch P. O. N. as well as movement of the brushes. The response of interrupter relay 320 to grounded battery by way of the contacts 304 of the switch P. O. N., the alternate contacts of the relay 309 to ground through the left-hand contacts of 90 the relay 303, prepares a circuit for secondary magnet 325.

When operated, the relay 320 establishes a self locking circuit which is independent 100 of the relay 309. This circuit extends through the contacts of the magnet 325, outer right-hand contacts of the relay 320 to ground through the contacts 313 of the relay 300. At the switch P. O. N. the transfer contacts switch the ground side of the trunk 105 L¹ from the transformers 324 to ground through the lowermost normal contacts of an all-trunks-busy switch 306 of this selector, thereby discontinuing the application 110 of the reverteive alternating currents over the toll line L. It may be mentioned that although currents from the sources 388 and 398 may have been present on the main conductors of the connection jointly with the first incoming impulse of alternating currents as released by the dial D, the 700 cycle currents of such impulses may meet and combine in effecting response of the relay 240, while the 1100 cycle current of the dial controlled impulse only, may effect response of 115 the relay 230. Therefore, proper and unmutilated reception of the first selective impulse will be had irrespective of the presence of the currents from the selector S. Pause of the distant dial following the first series 120 or train of impulses, permits the relay 309 at the switch S to restore and complete to ground at the left-hand contacts of the relay 303, the circuit prepared by the relay 320 for the magnet 325. The first response of this 125 130

magnet will move the brushes of the switch S in a secondary direction in seeking outlet through an idle trunk repeater circuit as the equipment TS. The first response of the magnet 325 also disconnects the relay 320 which releases, thereby disconnecting this magnet 325. In case the first repeater of a group may be busy, a private wiper 331 of the brush group will encounter ground potential which may be traced back through the lowermost contacts of the relay 310, the normal contacts of the magnet 325 (now de-energized), thence to grounded battery through the contacts 304 of the switch P. O. N. and the winding of the interrupter relay 320. The response of this relay again establishes its self-locking circuit to render it independent of the busy ground assumed as encountered by the brush 331, while this relay 320 also reestablishes the circuit for the magnet 325. This cycle of operations relative to alternative responses of the relay 320 and the magnet 325 will automatically continue until the brushes 395 and 396 arrive at the contacts of an idle repeater. Such idle condition will be characterized by absence of ground on a private segment as the segment 330 of a bank contact group B² of the repeater TS: Assuming now that the brushes have arrived at and respectively engaged the segments of the bank contacts of the repeater, absence of ground at the segment 330 prevents the shunting of the relay 310, therefore, current through the low resistance relay 320 over the path already traced as common to the brush 331 may be traced over a circuit through the high resistance winding of the switching relay 310 to ground through the uppermost normal contacts of the switch 306 and the outer left-hand contacts of the release relay 303. This effects response of the relay 310, while the relay 320 which is of the marginal type continues inert under the small current permitted by the high resistance of the relay 310. The two uppermost sets of contacts of the latter relay switch the trunk circuit L¹ from the battery supply at this selector S to the brushes 395 and 396 which now engage the corresponding segments of the bank group B², whence battery and ground connections extend through the contacts 353 and 351 of a reversing relay 352 and the winding of a battery supply or pulsing relay 350. The latter relay now responds to current through the loop formed by the trunk circuit L¹, and over an obvious circuit effects response of a slow-to-release relay 354. The right-hand contacts 355 of the latter relay apply ground potential by way of the segment 330, brush 331 and the lowermost alternate contacts of relay 310 to the release conductor 263, in substitution of the ground subsequently disconnected by release of the relay 303 following disconnection of the relay 300 at the in-

stant the relay 310 advanced the connection to the repeater TS.

In the present position of the selector S, a circuit for a release magnet 340 is prepared by way of the contacts 377 of the switch P. O. N. and the left-hand normal contacts of the relays 303 and 300 to the contacts 313, now separated, of the relay 310.

In case all of the trunks or repeaters in a sub-group, which includes the repeater TS, may have been busy, the magnet 325 would have advanced the brushes 395 and 396 beyond the bank contacts of the last repeater of the group, at which point devices (not shown) may effect operation of the switch 306, in the manner well known in the art. The uppermost contacts of this switch disconnect the relay 310 to insure that the trunk circuit L¹ will continue energized from this selector, while the transfer contacts of the switch 303 extend the ground side of the trunk circuit L¹ to ground through the secondary windings of transformers 324. A relay 345 under control of an interrupter 348 controls the application of alternating currents from the sources 388 and 398 to these transformers, whence resulting impulses may traverse the trunk circuit L¹ to flash either the distant dialing signal 41, the supervisory signal 75, or to be manifested as a tone signal in the receiver of the operator's telephone set, depending on the position of the keys in the cord circuit C at this time. The period or rate of this trunks-busy interrupter 348 may differ from the rate of the dialing signal interrupter 338, and the resulting difference in the rate of flashing of the distant signal will serve as an indication to the operator as to what condition has been encountered.

Returning to the moment when the repeater TS was seized in the present assumed connection as a result of which the relays 350, 354 were operated, signal and chain control relay 372 is energized by the current over an obvious loop path through a pulsing relay 400 of the selector S², the uppermost sets of normal contacts of a relay 430, trunk circuit L² to the repeater TS, where a bridge path may be traced from the conductor 360 of this trunk by way of the outer right-hand contacts of the release relay 354, the normal contacts 367 of a shunting relay 356, the left-hand winding of an electro-polarized supervisory control relay 370, contacts 371 of the relay 352, the right-hand winding of a signal and chain circuit control relay 372 and the right-hand pulse contacts of the relay 350 to the conductor 361 of the trunk circuit L². While the relay 372 responds to current through the path just traced, the relay 370 continues inert due to the fact that current is also present

over an obvious circuit through its right-hand winding to ground at the contacts 379 of the relay 354 is in opposition or differential relation with respect to the current 5 through the left-hand winding. The reason for this feature of the relay 370 will appear further on.

In describing the arrangement whereby the relay 280 may become effective to control the relay 225 at certain times only, attention will be directed to the relation of the contacts of the pulsing relay 270, whereby in responding to energization, the right-hand contacts may be closed in establishing 10 the loop circuit of the trunk L^1 , in advance of closure of the left-hand contacts through which ground potential, when present through the contacts of the alternating current relays 230 and 240 may become effective 15 with the contacts of the relay 280, and inversely, that during release of the relay 270 its left-hand contacts separate to open the grounding circuit to the contacts of the relay 280 in advance of the separation of 20 the right-hand contacts to open the loop circuit of the trunk L^1 . The relay 280 may respond substantially in unison with such control of the trunk circuit loop, therefore, during such control of the loop circuit by 25 the relay 270 in response to incoming impulses of selective currents, responses of the relay 280 may be considered as idle operations and therefore noneffective with the relay 225. It may further be pointed out 30 that the object in connecting the contacts of the relay 280 to receive ground potential through the contacts of the alternating current relays 230 and 240 is to take advantage 35 of the fact that no ground will be present 40 during the intervals alternating currents in the form of an impulse may be present in the latter relays. This effect in itself constitutes a complete guard during instants the relay 270 may be deenergized under such 45 impulses, and therefore the relay 280 is in this additional manner rendered ineffective at such times. From the foregoing it will be obvious that during absence of incoming impulses and during such times as the 50 relay 270 may be steadily retained in its operated position, while the relays 230 and 240 will be inert, ground potential will be present at the contacts of the relay 280. Therefore, any interruption of the loop circuit 55 of the trunk L^1 or reversals of current polarity therein as may be set up through operations as already described, at subsequent switches, may effect response of the relay 280 whereby the relay 225 will, in turn, be caused to respond in applying alternating currents to the toll line L .

The selector S^2 is substantially of the same type as the selector S and a detailed description of the progress of the present

connection through this switch S^2 is not 65 deemed necessary.

At the instant the relay 372 of the repeater TS responded as described, its left-hand contacts applied ground potential present through the normal contacts 366 of 70 the relay 356 to effect response of the reversing relay 352. The contacts of the relay 372 as shown, render it clear that this circuit for the relay 352 may be closed during the interval corresponding with the time 75 the three contact elements may be in engagement, one with the others while the relay may be under actual movement. Therefore, when the relay 372 may either be fully operated or fully restored, the relay 352 will be disconnected relative to the present described circuit for its momentary control. The momentary operation of the relay 352 effects a corresponding reversal 80 of current polarity in the loop of the trunk circuit L^1 . At the relay 280 this results in what may be described as a first momentary release followed by reoperation or a tendency to reoperate, then a second release 85 or a tendency to release, and a final reoperation of this relay 280. These effects result in the three contact elements of the relay 280 continuing in engagement, or in successively reengaging in a rapid manner, 90 one with the other, during an appreciable length of time, depending on the so-called follow effect adjustment of the contact elements and the time-constant of operation 95 characteristics of the relay 280. During such interval an obvious circuit for energization of the relay 225 will therefore be completed through the contact of the relay 280 as joined to ground over the left-hand contacts of the relay 270 and the contacts 100 of the alternating current relays 230 and 240. A condenser 244 shown in bridge on the winding of the relay 225 may be employed for prolonging the energization of this relay, as in supplying energy during 105 instants the contacts of the relay 280 may actually separate during rapid to and fro movements as described under the effects of current reversal in the loop circuit L^1 . During such predetermined energizations of the relay 225, the loop circuit of the line L will be switched from the trunk circuit L^1 to receive alternating currents from 110 sources 208 and 218, at 700 and 900 cycles per second, respectively, for controlling either one of the signals on the distant cord circuit C as already described in connection with currents sent back from the selector S for the same purpose as the present assumed 115 impulse relative to closing the circuits of the dial D and also for indicating that the dial may now be operated.

The next series of impulses released by the dial D, when received by the relays 230

and 240 effect interruptions of the trunk circuit loop L^1 , as already described, and now may set up corresponding responses of the pulsing relay 350 of the repeater TS. 5 The first release of this relay closes an obvious circuit for the response of the relay 356, the right-hand transfer contacts of which disconnect the path already traced through the left-hand winding of the relay 370, and the right-hand winding of the 10 relay 372 and connect a zero-resistance path by way of the right-hand contacts of the pulsing relay 350 to form a bridge on the trunk circuit L^2 . The left-hand contacts of 15 the relay 356 substitute at this time for the right-hand contacts of the relay 372 in closing a circuit CR commonly referred to as a chain relay circuit for displaying a signal (not shown) when all of the trunk circuits 20 of a sub-group may be busy. Separation of the contacts 366 of the relay 365 in advance of separation of the contacts 367 render the relay 372 ineffective with the relay 352 at the instant the relay 372 released 25 due to response of the relay 356. Under the arriving impulses, the relay 350 will effect corresponding interruptions of the trunk circuit L^2 , thereby causing the pulsing relay 400 of the second selector S^2 to effect 30 energizations of a primary magnet 408 under which the brushes 410, 411 and 412 will be advanced to a predetermined point, depending on the number of impulses received. On cessation of these impulses a series relay 409 of this selector may release, following which a secondary motion magnet 407, 35 under the control of an interrupter relay 406, may automatically advance the brushes 410, 411 and 412 in a secondary direction 40 in seeking an idle connector switch as the connector K.

In describing operations which may take place in case all of the connectors of a sub-group to which the selector S^2 has access 45 have been found busy, the magnet 407 will advance the brushes 410, 411 and 412 beyond the last trunk of such group at which point mechanical means (not shown) will cause operation of the trunks-busy switch 50 401. The uppermost contacts of this switch disconnect the switching relay 430 to insure that the trunk circuit L^2 may continue energized from this switch S^2 , while the make-before-break type contacts of this 55 switch transfer the ground side of the trunk L^2 from full potential ground to ground through the winding of a relay 402. Response of the latter relay to current in the loop circuit of the trunk L^1 , connects the 60 secondary windings of transformers 404 in bridge on the battery supply leads which extend through the normal contacts of the relay 430 to the main conductors of the trunk. A relay 435 controlled by an interrupter 65 438 controls the application of all

ternating currents at 700 and 900 cycles per second, respectively, from the sources 481 and 482 to the transformers 404. Accordingly, impulses formed of these currents may traverse the connection to the toll line L^2 and thereover be manifested by flashing of the distant dialing signal 41, or the supervisory signal 75, as an indication to the operator that all trunks of the selected group are busy. 75

Assuming now that the last movement of the switch S^2 brought the brushes 410, 411 and 412 into engagement with terminals 413, 414 and 415 respectively of the connector K which may be idle, such idle condition will be characterized by absence of ground on the terminal 415 thereby permitting grounded battery through the low resistance marginal relay 406 of the selector S^2 to complete a circuit through the high resistance winding of the switching relay 430 which may respond to disconnect the trunk circuit L^2 from the battery supply circuits of the selector S^2 and extend the trunk circuit L^2 through to the brushes 413, 414 and 415. The trunk circuit L^2 may now be energized by grounded battery supplied through a pulsing relay 416 and the contacts 420 and 421 of a back-bridge relay 425. 95

The momentary interruption of the trunk circuit L^2 effected by operation of the relay 430 in extending the trunk circuit through the switch S^2 , results in momentary release followed by reoperation of the relay 372 100 at the repeater TS. The left-hand contacts of the relay 372 accordingly establish the circuit already described through the relay 352 thereby effecting momentary response of the latter relay to cause a momentary reversal of current polarity in the trunk circuit L^1 in response to which the relay 280 will effect momentary response of the relay 225 in applying an impulse of alternating currents over the toll line circuit to display 110 the dialing signal and to render the dial at the distant operator's position effective for sending another series of selective impulses. 105

At the repeater TS the relation of the 115 right-hand group of contacts on the relay 356 as shown, is such that in response to energization, the normal contacts 366 will separate in advance of the separation of the adjacent normal contacts 367, and inversely, on deenergization of this relay, the contacts 367 will close in advance of closure of the contacts 366. As already described, the contacts 366 extend ground potential to the left-hand contacts of the relay 372 to render this relay effective in setting up momentary energizations of the relay 352 during actual movement of the relay 372 while the contacts 367 normally prepare the circuit 120 through the left-hand winding of the relay 125 430. 130

370 and the right-hand winding of the relay 372, previously traced as including the right-hand contacts of the relays 350 and 354 in completing a direct current path energized by current from over the trunk circuit L². Therefore, movement of the relay 372 in either direction, when such movement may be due to action of the relay 356 will be ineffective with the relay 352, 10 and the relay 280 accordingly will not be affected and no impulse of alternating currents will be sent to the line L by the relay 225 at such times. From the foregoing it will be obvious that the left-hand contacts 15 of the relay 372 may be rendered effective with the relay 352 at such times only as the relay 356 may be at rest in its inert position, and since the latter relay may be under energization during periods corresponding only with the actual reception of a train or series of impulses for controlling subsequent switches as the selector S² or the connector K in the present drawings, it will be obvious that the relay 372 may be 20 rendered effective to cause the relay 225 to send a reverte impulse of alternating currents over the line L only at the instant the repeater TS may have been seized and at such other times as when the relay 372 25 may momentarily respond to the cutting through of trunk circuits at subsequent switches or to other operations as will presently appear. To insure proper responses at such times, the time constant of operation 30 of the relay 372 is to be within the time interval present between the separation of the normal contacts and the closure of the forward contacts on subsequent switching relays, as the relay 430 of the selector S², 35 in the connection now being traced. The importance of the relation between the relays 356 and 372 relative to control of the relay 352, may further be emphasized by pointing out that except for the arrangement just described, a reverte impulse of 40 alternating currents would become effective at the distant cord circuit to display the dialing signal 41 and to render effective the dial D, immediately following the reception 45 of a first series of impulses through the repeater TS for advancing the brushes of the second selector switch S² to a predetermined point in a primary direction. Therefore, 50 such signal and releasing of the distant dial would be premature as no time would have been allowed for completion of the movement of the brushes 410, 411 and 412 in a secondary direction as already described as effected through automatic control by 55 the magnet 407 in conjunction with the interrupter relay 406, whereby either an idle third selector switch (not shown) or an idle connector switch, as the connector K, 60 may have been reached and seized for use. A similar condition would also be presented

relative to dialing through each one of any subsequent selector switches which may be present in situations well understood in the art, where such switches may be required following the selector switch S². 70

At the connector K the energized position of the pulsing relay 416 and the release relay 417 result in ground potential being connected by way of the segment 415 and the brush 412 to a release conductor 75 466, thence over an obvious circuit for retaining the switching relay 430 at the switch S². At the instant the relay 417 responded, its right-hand contacts, during the interval 80 that the three contact members were in engagement, one with the other, completed a circuit which may be traced from grounded battery, through the parallel connected contacts of two alternating current relays 484 and 485 and the lowermost or locking winding of a ringing relay 451 to ground at the contacts of the relay 417. On response of the relay 451 its self-locking or next lowermost contacts establish the circuit already 85 traced through its lowermost winding, 90 thence over another lead to ground by way of the right-hand alternate contacts of the relay 417. The contacts 452 and 465 of the relay 451 disconnect a ringing equipment 450 and at the present time idly connect the main conductors through to the contacts of a brush disconnect relay 440 of the connector. The object in retaining the relay 451 energized at this time is to insure that 95 ringing current may not be applied to a called station except under control of the originating operator, as presently will appear. In response to the next train of incoming impulses comprising the first impulses for moving the connector K, the pulsing relay 416, during moments it may be in its deenergized position, completes a circuit from ground potential by way of the contacts 100 433 of the relay 417 and the contacts 105 434 of an off-normal switch 455, the winding of a slow-to-release relay 418 and a primary magnet 419 to grounded battery. The first energization of the magnet 419 in addition to advancing the brushes 460, 461 and 447 also effects actuation of the off-normal switch 455, and, due to the operated position of the relay 418, the circuit of the magnet 419 will now extend by way of the inner alternate contacts of the latter relay, the contacts 436 of the switch 455, the contacts 110 433 of the relay 417 to ground through the normal contacts of the pulsing relay 416. The present series of impulses serve to advance the brushes 460, 461 and 447 to a pre-determined point, following which the pause 115 at the distant dial D results in release of the relay 418 to prepare a circuit which may be traced from grounded battery, through the winding of a secondary magnet 480, the contacts 441 of the relay 440, the contacts 120 125 441 of the connector K, the contacts 433 of the relay 417 to ground through the normal contacts of the pulsing relay 416. The present series of impulses serve to advance the brushes 460, 461 and 447 to a pre-determined point, following which the pause 125 at the distant dial D results in release of the relay 418 to prepare a circuit which may be traced from grounded battery, through the winding of a secondary magnet 480, the contacts 441 of the relay 440, the contacts 130

437 of a busy relay 439, the innermost right-hand normal contacts of the relay 418, thence by way of the contacts 436 of the switch 455 and the left-hand alternate contacts of the relay 417 to ground through the normal contacts of the pulsing relay 416.

At the instant the relay 418 released, its make-before-break right-hand contacts momentarily applied ground potential as present through the lowermost contacts of the switch 455, to grounded battery through the switch 467 to lowermost winding of the reversing relay 425. The momentary response of the latter relay to current in this circuit effects momentary reversal of current polarity through the trunk circuit L^2 . At the repeater TS, the left-hand winding of the relay 370 being in series with the trunk loop, this reversal of current renders the current effect in the two windings of the relay 370 cumulative, therefore, this relay will momentarily respond and at its outer right-hand contacts apply ground potential to effect similar response of the relay 352. Although the relay 372 at the repeater TS will also momentarily release at this time due to reversal of current polarity in the trunk circuit L^2 , its effects relative to the relay 352 will be substantially an overlapping operation with the effects established by the relay 370. The relay 352 in turn, momentarily reverses current polarity in the trunk circuit L^1 which will be effective with and translated by the relays 280 and 225 in applying an impulse of alternating currents to display the distant dialing signal 41 and to render the dial D operative. The object in supplying ground potential through forward contacts on the off normal switch 455 to the right-hand contacts of the relay 418 is to render these contacts ineffective with the relay 425 on response of the relay 418 at the beginning of the first series of impulses to this connector, but to render these contacts effective with the relay 425 during release of the relay 418 on cessation of such incoming impulses.

Under the next and last series of impulses for completing the present assumed connection, the relay 416 may actuate the magnet 480 in advancing the brushes 460, 461 and 447 into engagement with the bank terminals 462, 463 and 445 respectively of the line circuit to the station B. During such travel of the brushes 460, 461 and 447 the bank contacts of intervening line circuits will be passed over, and the private wiper 447 may idly encounter either battery potential or ground potential respectively depending on whether an intervening line may be idle or busy. To insure that the brush disconnect relay 440 may not be prematurely operated due to battery being encountered on the bank contact of an idle line, a slow-to-release relay 442 is connected to be energized in par-

allel with the magnet 480. Under operation, the left hand armature of the relay 442 switches the private brush 447 from the uppermost or operating winding of the relay 440 to the busy relay 439, over a path through the lowermost contacts of the relay 440 and the winding of the relay 439 to grounded battery. It will be obvious that the relay 439 may respond each time the brush 447 may pass over and receive ground potential from the private segment of a busy line, and in order that the outer right-hand normal contacts of the relay 439 may not disconnect the magnet 480 at such time, the right-hand contacts of the relay 442 are connected to form a by-path around these contacts of the relay 439.

Assuming that the brushes 460, 461 and 447 have completed their travel and are now at rest in engagement with the respective segments 462, 463 and 445 of the bank terminals, and assuming further as a first illustration, that the line circuit of the station B is busy, as a result of which ground potential will be present on the segment 445, through means not shown but well understood in the art, the relay 439 may initially respond over the circuit already traced by way of the contacts 448 of the relay 442, thence over the brush 447 to the assumed ground at the segment 445. Immediately following this, release of the relay 442 will take place due to the pulsing relay 416 now being retained in its operated position as a result of cessation of the last series of impulses. Although the contacts 476 of the relay 442 reconnect the brush 447 to the uppermost winding of the relay 440 the opposite end of this winding will now stand open at the contacts 475 of the busy relay 439, while the make-before-break effect at the left-hand contacts of the relay 442 permit the contacts 432 to close and substitute for the ground potential supplied by way of the brush 447, a circuit through the winding of a relay 497 and the right-hand innermost alternate contacts of the relay 439, thence to ground through the outer left-hand contacts of the release relay 417. In this self-locked circuit of the relay 439, response of the relay 497 connects a battery interrupter 498 by way of the inner left-hand alternate contacts of the relay 439 with the uppermost main conductor lead from which a path may be traced through the upper winding of the relay 425 to ground. It will be obvious that the latter relay may respond to the interrupter 498 in effecting successive reversals of current polarity in the trunk circuit L^2 . As already described such reversals may be translated through the preceding switches and equipment to apply alternating currents over the line circuit L to flash either the distant dialing signal 41, the supervisory signal 75 or to be manifested as tone in the re-

ceiver of the operator's set, depending on the position of the keys in the cord circuit C. During the sending back of a busy signal the outer left-hand contacts of the relay 439 5 join a busy tone transformer 493 with the main circuit of the connection. This serves in situations where a connector may also be employed for completing local as well as toll connections, and is not essential to toll 10 traffic.

Let it now be assumed as a second illustration, that instead of the line of station B having been found busy this line was idle at the moment the brushes of the connector 15 K engaged its terminals. Under such condition battery potential by way of cut-off relay 446 for clearing the line of station B of associated equipment (not shown), the segment 445, brush 447, contacts 476 of the 20 relay 442, uppermost winding of the relay 440, thence to ground through normal contacts 475 of the relay 439 and the outer left-hand contacts of the release relay 417 effects response of the relay 440. This closes 25 a circuit from grounded battery through the lowermost locking or retaining winding of the relay 440, its self-locking contacts 444, thence to ground through the right-hand alternate contacts of the release relay 417. 30 Other circuit changes effected by response of the relay 440 may be described as separation of its lowermost contacts to disconnect the busy relay 439, disconnection of the magnet 480 at the third lowermost contacts 441, 35 while during movement of the third lowermost make-before-break contacts, ground potential is momentarily applied through the winding of a relay 487, thence to grounded battery through the parallel connected contacts of the two alternating current relays 484 and 485. Response of the relay 487 40 establishes its self-locking circuit through its right-hand contacts to ground at switch 454, while the left-hand contacts of this relay join a grounding interrupter 488 to the 45 uppermost main conductor energized by current from grounded battery, through the left-hand winding of the relay 416, contacts 420 of the relay 425. During each instant 50 this current may flow to ground through the interrupter 488 although the battery supply relay 416 will continue energized, cessation of current in the loop circuit of the trunk 55 L² will result. In response to this, release 55 of the relay 372 at the repeater TS will result in momentary response of the relay 352 to correspondingly set up a reversal of current polarity through the loop of the trunk circuit L¹. In a manner similar to 60 that already described, the relays 280 and 225 will translate such reversal of polarity into an impulse of alternating currents (700 and 900 cycles) over the line L to be manifested on either the distant dialing signal 41, 65 the supervisory signal 75 or as a tone indi-

cation in the receiver of the operator's telephone set, depending on the position of the keys of the cord circuit. The speed of the interrupter 488 may be such that resulting successive responses of the relay 372 will 70 serve to flash the distant signal in a characteristic manner readily distinguishable from the dialing, trunks busy or the line busy signals already described. To this end, irregularity in the flashings may be controlled 75 by the interrupter 488 in certain situations in a manner to effect a predetermined number of rapid flashes followed by an interval of rest. This distinctive signal is for the purpose of indicating to the controlling operator that the connection has been extended 80 to the line of the station wanted, and that ringing may be proceeded with, relative to calling this station.

Further switching effects resulting from 85 the operated position of the relay 440 may be described as steady ground applied over the contacts to prepare a path by way of the lowermost alternate contacts 443 of the ringing relay 451 and the lowermost normal 90 contacts of the relay 425 from which a lead 457 extends to equipment (not shown) for energizing an attendant's signal in case ringing of the called line does not take place within a predetermined time. Such an arrangement might take the form of the device shown in the patent to Sperry, No. 1,406,233, granted February 14, 1922, in which the lead from the right-hand armature of relay O corresponds to the present 100 lead 457 and the signal 6 is the signal hereinbefore mentioned. The contacts 449 of the relay 440 apply ground potential to establish and continue a busy test condition by way of the brush 447 with the segment 105 445 of the line of station B, and also to effect shunting of the uppermost winding of this relay 440, while the contacts 453 and 464 of this relay join the main conductors 110 of the connector through to the main conductors of the line circuit of station B.

In order to ring the station B the operator may momentarily operate the non-locking ringing key 55 of the cord circuit C, thereby applying ringing currents at 700 and 115 900 cycles per second from sources 70 and 71 to the main conductors of the present connection. These currents may traverse the line L and the distant connection as extended through the trunk circuits L¹ and L² 120 to complete circuit through the two serially connected relays 484 and 485 joined in bridge across the main conductors at the connector K. These relays may be of the type already referred to as preferable for 125 the relays 230 and 240 and under effect of the ringing currents separation of their contacts results in the deenergization of the relays 451 and 487. The relay 451 switches the main conductors as now joined to the 130

- line circuit of the station B from connection with the toll line L to receive ringing current from the ringing system 450. Restoration of the relay 487 disconnects the derived circuit 5 from the upper conductor of the trunk circuit L² through the interrupter 488, thereby discontinuing the reverte impulse effects described as indicating that the connection has been completed to the station B.
- 10 Coincident with starting of the ringing operation, it is arranged that an energized condition of the supervisory signal 75 on the cord circuit C will be assured. To this end, the operated position of the ringing 15 key 55 at its lowermost or side contacts switches the circuit from grounded battery as present through the left-hand alternate contacts of the relay 58 (now operated) from the path to the armature of the relay 9 to a 20 path which extends through the right-hand alternate contacts of the relay 58 to the lowermost winding of the relay 9. This insures that the armature of the latter relay will take up its lower bias, while the relay 25 6 will be shunted, thereby assuring that the relay 7 may be energized to disconnect the relay 6 and display the signal 75. The make-before-break relation of the lowermost set 30 of transfer contacts on the key 55 insures that following release of this ringing key the signal 75 will continue energized and therefore may be extinguished only on response from the station B as will now be described.
- 35 During the ringing period the condenser 496 shown joined from the upper one of the main conductors by way of the normal left-hand contacts of the relay 439 to the same main conductor of the connection at a point to the left-hand side of the ringing relay 451, 40 is for the purpose of affording so-called ring back induction which may traverse the connection over the toll line and serve as an audible signal in indicating to the outward operator that ringing current is actually being applied to the line circuit of the station 45 wanted.
- 45 As well understood in the art, removal of the receiver from its switchhook at the station B in response to this call will result in the direct current component from the ringing system 450 by way of the uppermost winding of the relay 451 effecting so-called tripping or initial response of this relay, following which it will be retained as self 50 locked under control of the relays 484, 485 and 417. This switches the circuit of the line to the station B from the ringing system 450 to the connection as joined to the toll line L.
- 55 In describing supervisory control whereby the signal 75 of the cord circuit C will be retired due to response at the station B, talking battery supplied through the back bridge relay 425 to the station B energizes this relay to reverse the polarity of

the battery current through the trunk circuit L², and also to shunt the relays 484 and 485. At the repeater TS this reversal of current through the left-hand winding of the relay 370 establishes a cumulative action with the current present in the right-hand winding of this relay to effect its response and at its right-hand contacts ground potential is applied over an obvious circuit through the winding of the relay 352 to grounded battery. Response of the latter relay effects reversal of current through the trunk circuit L¹, thereby effecting momentary release of the relay 280 to effect response of the relay 225, whereby an impulse of alternating currents at 700 and 900 cycles per second will be applied over the line circuit L. At the cord circuit C the dialing key 44 having been restored, arrival of the described impulse of alternating currents effects operation of the relays 80 and 81 connected in bridge on the main conductors of the cord circuit. A condenser 98 joined across the right-hand winding of the relay 77 serves as a by-pass for these relatively high frequency alternating currents with respect to this winding of the relay 77 as connected in series with the relays 80 and 81. Under energization, the relays 80 and 81 separate their parallel connected contacts to disconnect the circuit from grounded battery as connected to the armature of the relay 9, now on its lower contact stop 15. This disconnection of current from the lower winding of the relay 9 permits current present through the upper winding of this relay over the circuit through the relay 7, to effect opposite bias of this relay 9. Therefore, on cessation of the incoming impulse of alternating currents, restoration of the relays 80 and 81 will re-establish the full potential of the grounded battery by way of the armature of the relay 9, its upper contact stop 68 and upper winding to the sleeve path of the connection. In this condition of the circuits and position of the relay 9, it will be obvious that the winding of the relay 7 will be shunted and the resulting release of this relay will disconnect the signal 75 and apply current from grounded battery through the winding of the relay 6 and the lower winding of the relay 9 over the sleeve path of the connection. The circuits of the supervisory signal 75 may continue in the present described deenergized condition during conversation between the station A and the station B.

55 In case the subscriber at the calling or home station A may flash during this period, the signal 87 will be affected as already described, and in the event that the party at the station B may flash the switchhook at that point, the signal 75 will be controlled as follows:

60 In the operation of flashing, the first de-

pression of the switchhook at the station B will effect release of the battery supply relay 425 to reverse the polarity of the current in the trunk circuit L^2 , thereby setting up differential effects in the relay 370 at the repeater TS to cause this relay to release and disconnect the relay 352, thereby reversing the polarity of the current through the trunk circuit L^1 . This reversal translated through the relays 280 and 225 results in the application of currents at 700 and 900 cycles per second to the toll line L. At the cord circuit C this impulse effects joint response of the relays 80 and 81 to disconnect grounded battery from the armature of the relay 9 as connected by way of its upper contact stop 68 and upper winding to the sleeve circuit of the connection. Due to absence of current in this upper winding of the relay 9 the current present through the normal contacts of the relay 7, the winding of the relay 6 and the lower winding of the relay 9 to the sleeve strand of the connection will result in opposite biasing of this relay. On cessation of the incoming impulse of alternating currents, the circuit will be established from grounded battery by way of the armature, lower contact stop 65 and lower winding of the relay 9 over the sleeve circuit. Presence of grounded battery at full potential on the lower contact stop of the relay 9 results in shunting down the relay 6 which thereupon may release and apply grounded battery through the winding of the relay 7 and the upper winding of the relay 9 to the sleeve circuit. Response of the relay 7 disconnects the relay 6 and applies grounded battery to energize the signal 75.

The release of the switchhook at the station B as the second movement in the flashing operation, results in reversals of current polarity in the trunk circuits L^2 and L^1 as already described, whereby another impulse of alternating currents will revert over the line L and effect response of the relays 80 and 81 on the cord circuit C. Operations similar to those first described will then take place to result in the armature of the relay 9 being moved to its upper bias, while the relay 7 will be released to extinguish the signal 75 and to connect grounded battery through the circuit of the relay 6. In this manner it will be clear that irrespective of the number of times the switchhook at the station B may be manipulated in a flashing operation, the signal 75 will be flashed in response to the movements of the switchhook, and finally, that this signal may either be displayed or retired, depending on whether the receiver has been left on or left off its switchhook at the conclusion of the flashing operations.

It will be pointed out that the armature of the relay 9 is to be provided with suitable biasing means which may be in the form of

a spring 36 shown in the drawing. This biasing effect insures that under a no current condition for this relay as when the plug 3 may not be in use, the armature will be moved to and retained on its lower contact stop 65, the position in which it is shown in the drawing. As may be understood from the drawing, the two windings or coils of the relay 9 are connected to be energized in differential relation, one with the other, and during actual transition or movement of the armature, current will be present in one of the coils only and that on the side to which the armature may be travelling. During periods the armature may be at rest in either one of its positions, current of a predetermined maximum strength in the coil corresponding with the position of the armature will be effective to retain the armature against counter effect of current of a predetermined minimum strength in the opposite winding. The low current strength condition for the upper coil is present when the winding of the relay 7 may be in series with this coil, while the low or minimum current condition for the lower coil is had during periods the winding of the relay 6 may be in series with this coil.

In general, during the automatic setting up of a connection the dialing key 44 will remain in its operated position, until the dialing operations have been completed therefor, no revertive current effects from over a toll line circuit may become effective with the supervisory control relays 80 and 81, and the signal 75 may continue energized until extinguished as a result of response at the distant called station. In the event, however, that as heretofore mentioned, the key 44 may have been temporarily restored before completion of the dialing operations and revertive impulses due to effects resulting from the extending of a connection through a distant switch may have retired the supervisory signal 75, this signal will be displayed due to operation of the ringing key 55 in calling the distant station, as previously described.

Referring to the condition of the circuits at the repeater TS during the talking period, additional condensers 322 and 373 under control of the reversing relay 352 are joined in parallel with condensers 374 and 375 respectively, permanently wired in the main conductors of the connection. The additional capacity will be present during talking periods in order to better the telephonic transmission, while disconnection of the additional capacity during the time a connection is being built up through the repeater serves to guard against interference with the operation of the pulsing relay 350 as otherwise may occur due to reactive or surge currents from condensers of higher capacity during the reception of selective impulses.

In the talking position of the circuits, the left-hand contacts of the relay 370 establish a shunt path on the normal contacts 367 of the relay 356 while the inner right-hand contacts of the relay 370 establish a shunt path on the right-hand or pulsing contacts of the relay 350. These shunt paths are provided to act as a safeguard to a connection in avoiding any effect in the event that the 10 protected contacts may momentarily be interrupted due to inadvertent movement of the dial or the switchhook at a calling station in situations where a repeater may be subject to use on local service connections as 15 well as on toll connections similar to the connection just described. In this regard it may be pointed out that where a repeater may be used for the present toll service only, such safeguards will not ordinarily be required as the system may not respond to transient current effects.

In describing operations whereby the connection may be broken down, removal of the plug 3 from the jack 4 disconnects the relay 22 which, although of a slow-to-operate type, may release quickly and apply current at 700 and 1100 cycles per second from the sources 20 and 21 by way of the alternate contacts of the relay 10 (still energized) to the toll line L. Separation of the contacts 28 of the relay 22 disconnect the relay 10 which is of a slow-to-release type, therefore, during the interval corresponding to the difference in time of the releasing of relays 22 and 10 the alternating currents may traverse the line circuit L. At the inward end of the line circuit these alternating currents effect joint operation of the relays 230 and 240 to release the relay 270 which in turn 10 opens the loop circuit of the trunk L¹. At the repeater TS this results in release of the battery supply or pulsing relay 350 and, in turn, disconnection of the release relay 354. The duration of the impulse of alternating 15 currents from over the toll line L is of sufficient length to permit the slow-to-release relay 354 to restore and disconnect earth potential from the path already traced through the switch S to the release conductor 263. This permits the relay 255 to restore, thereby disconnecting the relay 270 and switching the relay 250 to continue energized over the circuit through the contacts of the alternating current relays 230 and 240 to ground. As already described, the relay 250 is of a slow-to-release type and is continued energized over the release lead 263 during the period of the connection. The 20 duration of the incoming impulse of alternating currents may be slightly longer than the time required for the restoring of the release relay 354 at the repeater TS, and, therefore, this alternating current interval 25 may overlap the moment when the relay 250 may have been switched by the relay 255 to

come under control of the relays 230 and 240. This overlap portion of the impulse interval will not be of sufficient length, however, to in turn, permit release of the relay 250 at this time. Therefore, reseizure of the 70 inward equipment may not take place during this break-down operation.

Proceeding with the description of the release operations through the various switches, removal of ground from the release conductor 263, due to restoring of the relay 354 at the repeater TS, permits release of the switching relay 310 at the selector S. The ground contacts of this relay complete the circuit prepared, whereby the release magnet 340 may be energized to restore the switch to normal position. Disconnection of the loop circuit of the trunk L² at the right-hand contacts of the relay 350 (also at the outer right-hand contacts of the relay 354) of the repeater TS, results in release of the battery supply relay 416 at the connector K, and, in turn, disconnection of the release relay 417. Disconnection of ground at the left-hand contacts of the latter relay from the release conductor 473, results in de-energization of the switching relay 430 of the second selector switch S². Thereupon, the grounding contacts of the latter relay complete the circuit prepared for energization of the release magnet 469, whereby the selector will be restored to normal position.

Assuming now as a first example, that the receiver has not as yet been replaced on its switchhook at the station B, the separated position of the right-hand contacts of the relay 417 although removing a first ground connection from the lowermost or locking windings of the relay 440, the second ground will however, be present as already traced through the contacts 443 of the relay 440 for retaining this relay. This condition results due to the relay 425 continuing energized in supplying battery to the station B. The relay 451 held locked in parallel with the relay 440 at this time, continues energized to prevent application of ringing current to the line B, while the relay 440 continues to retain the selector K joined to the line circuit of the station B. In this condition of the connector a circuit may be traced from ground potential, through the normal contacts of the pulsing relay 415, the left-hand normal contacts of the relay 417 and the contacts 424 of the relay 425 to a lead 458. This lead as in the case of lead 457 will be understood as extending to equipment (not shown) whereby after a predetermined period, an attendant's signal will be displayed. As well understood in the art, the reason for retaining the connector K as just described until the receiver at the station B may have been returned to its switchhook, is principally for the purpose of preventing switches on the line B from becoming

ing active with regard to so-called plunging in on trunks to secondary line switches or to first selectors as otherwise would occur, in the same manner as when a call may originate at the station B. On the receiver being replaced on its switchhook at this station, release of the relay 425 disconnects the ground connection just mentioned thereby permitting release of the relays 440 and 451. 5 Following this, a circuit may be traced from grounded battery, through the winding of the release magnet 490, contacts 491 of the switch 455, contacts 492 of the relay 425 and thence to ground through the left-hand normal contacts of the relays 417 and 416. 10 Energization of the magnet 490 results in restoration of the connector K to normal position.

Assuming as a second example that the receiver had been returned to its switchhook at the station B in advance of disconnection by the operator, release of the battery supply relay 425 removes the ground connection as paralleled with the ground through the right-hand contacts of the relay 417. 20 Therefore, when the cord C is taken down and the disconnection operations have progressed as already described, to the release of the relay 417, separation of the right-hand contacts of this relay will result in de-energization of the relays 440 and 451. 25 Following this the release magnet 490 will respond in restoring the connector K to its normal position.

30 In case the cord C may not be taken down within a predetermined time following disconnect at the station B ground potential over the contact 443 of the relay 440 by way of the lowermost contacts of the relay 451 and the lowermost normal contacts of the relay 425 may effect display of an attendant's signal already mentioned as reached by the lead 457.

35 In the event that disconnect may be made prematurely at the station B the operator may re-ring this station by momentarily operating the ringing key 55 on the cord circuit C. The resulting impulse of alternating currents over the toll line effect response of the relays 484 and 485 to disconnect the circuit of grounded battery as locked through the lower winding of the relay 451, during the time the circuits of the connector may have been in the talking or the non-ringing position. Release of the relay 451 joins the ringing current system 450 with the line to the station B, and response at this station will result as already described.

40 In situations where it may be desired to employ so-called automatic ringing of the bell at a station under call, the lead 478 intermediate the locking winding of the relay 451 and the right hand normal contacts of the relay 417 of the connector K may be

dispensed with, while a lead 477 which may receive ground potential through the second uppermost normal contacts of the relay 451 may be substituted for the direct ground connection present at the right-hand contacts of the relay 487 in which case the switch 454 will be across the right-hand contacts associated therewith. Under this condition it may readily be understood that the ringing relay 451 normally will be inert 70 during the progress and immediately following the completion of a connection through the connector. Therefore, following response of the brush connecting relay 440, ringing current will be applied to the line 75 connected. Response on such line will result in current through the uppermost winding of the relay 451 effecting initial operation 80 of this relay, following which, its self-locking contacts will complete the circuit from ground potential at the right-hand alternate contacts of the relay 417 to grounded battery through the lowermost winding of this ringing relay. The energized position 85 of the relay 451 places the circuits in the talking position in which they will continue until the connection finally may be broken down, as already described, while ground will be removed from the lead 477 to effect 90 release of the relay 487 in disconnecting the grounding interrupter 488.

95 In situations where it may be desired to retain the so-called re-ring feature in connection with the arrangement just described 100 whereby ringing of the called station may start automatically at the instant the connection may have been completed, the alternating current relays 484 and 485 may be employed as shown in the drawing. Therefore, assuming that the connector K is now 105 joined to the line circuit of the station B and following a first response, the receiver may have been returned to its switchhook at that point, the controlling operator desiring further communication with this station 110 may momentarily operate the ringing key 55 of the cord circuit C. The resulting impulse of alternating currents in operating the relays 484 and 485 effect release of the ringing relay 451 at the connector K. The resulting application by this relay of ringing current to the line of station B may be 115 followed by a cycle of operations similar to those, already described relative to first reaching this station.

120 In the event that in connection with the arrangement for automatic starting of the ringing of a connected station it may not be desired to retain the re-ring feature just described, the alternating current relays 484 and 485 may be dispensed with, the current supply leads to the relay 487 and to the lowermost winding of the relay 451 may then be connected directly to grounded battery.

125 In the connection just traced in joining

the station A with the station B the toll line L was shown and described as terminating directly in a first selector switch S. In considering a similar connection between the stations A and B, let it now be assumed that the line circuit L may terminate in a first preselector or primary line switch PL Fig. 2^A, and that this switch, in turn, may engage a secondary line switch SL before entering the first selector switch S. Therefore, in substituting the equipment of Fig. 2^A for the equipment shown at R between lines AA and BB in Fig. 2, let it be assumed that in response to insertion of the plug 3 of the cord circuit C into the jack 4 of the toll line L, an impulse of alternating currents arrives at the terminating equipment E² and energizes alternating current relays 230 and 240 for a predetermined period of time. At Fig. 2^A this results in de-energization of a slow-to-release relay 250^A through which grounded battery may be traced as normally present by way of the normal contact of a line switch magnet 255^A and the normal contacts of the relays 230 and 240 to ground. Release of the relay 250^A connects grounded battery over an obvious circuit through the uppermost winding of the magnet 255^A, which thereupon responds. The contacts of this magnet switch the relay 250^A from the contacts of the relays 230 and 240 to a release conductor 263^A and substitutes the pulsing relay 270 to come under control of the alternating current relays 230 and 240. The uppermost armature of the magnet 255^A causes a plunger 256 to distend an associated group of switching springs 257 whereby the release conductor 263^A may be closed through the outer left-hand contacts of this switch to the corresponding contacts of the secondary switch SL while the outer right-hand contacts of the switch PL connect ground potential by way of the uppermost winding of the magnet 285 of the switch SL, thence over the normal contacts of this magnet and the winding of a relay 277 to grounded battery through the winding of a magnet 295 of the master switch equipment MS. The response of the magnet 285 closes a selflocking circuit from grounded battery, through its lowermost winding now joined in series with the upper winding, to the ground just traced at the outer right-hand contacts of the switch PL. These contacts of the magnet 285 also disconnect the circuit through which the relay 277 responded while in series with the upper winding of the magnet 285. The response of the slow-to-release relay 277 closes a path from the extended release conductor 263^A to the ground now present at the outer right-hand contacts of the switch PL. This ground also effects energization of a magnet 276 of the master switch equipment MS over an obvious circuit in initiating

movement of this switch, for purposes well understood by those skilled in the art. The plunger 286 of the magnet 285 distends a bank spring group 287 in joining the release conductor 263^A through to a corresponding lead to the first selector switch S, while the outer right-hand contacts of this group 287 apply ground potential to the magnet 297 of the associated master switch MS to initiate movement of this switch, as well understood in the art. In the present operated positions of the switches PL and SL the two main conductors of the trunk circuit L¹ will be established over obvious paths in joining the equipment E² to the main conductors of the first selector switch S. At this switch, response of the relays 300 and 303 result in application of ground to the release lead 263, (263^A) in substitution of ground supplied by the slow-to-release relay 277. Response of the relay 275 to the ground on the release lead 263 establishes the busy test conditions for the jacks 200, 251 and 299, the bank contacts B¹ and the busy signal 254 as previously described.

Following seizure of the selector switch S by way of the primary and secondary line switches PL and SL, it will be obvious that selective impulses originated by the distant dial D may be translated through the alternating current relays 230 and 240 and the pulsing relay 270 to progressively advance a connection through the first selector S to the repeater TS, and thereafter successively to the second selector S², the connector K and finally to the line of the station B, in a manner similar to that already described for the first assumed connection. Since the main conductors of the connection merely extend through respective contacts of the line switches PL and SL it will further be clear that signals relative to the progress of the connection through the various switches, supervisory control signals and ringing signals may be transmitted in the same manner as already described for the first connection.

It may further be understood that the relay 250^A and the magnet 255^A of the primary line switch PL may correspond respectively with the relays 250 and 255 as shown at R, Fig. 2. Therefore, releasing of the present assumed connection due to removal of the plug 3 from the jack 4 at the outward position will result in the relay 303 at the selector S disconnecting ground from the release lead 263, 263^A, through the preceding switches SL and PL, thereby permitting the magnet 255^A to restore and switch the relay 250^A to come under control of the alternating current relays 230 and 240, while also disconnecting the pulsing relay 270. The restoration of the magnet 255^A disconnects and permits release of the magnet 285 of the switch SL, which in turn restores to permit the equipment of

this secondary line switch SL to restore to normal. The disconnect operations through the switches S, repeater TS, second selector S² and the connector K may progress in the same manner as that already described in the breaking down of the first connection discussed.

In describing operations whereby a connection over the toll line L may be handled on a manual basis, the plug 3 of the cord circuit C may be inserted in a jack 90 of the toll line L. For the sleeve path of this connection a circuit may be traced from grounded battery, through the contacts 35 of the talking key 19, the left-hand normal contacts of the relay 58 (now inert), the lowermost normal contacts of the ringing key 55, the parallel connected contacts of the alternating current relays 80 and 81, the armature, stop 65 and winding 13 of the relay 9, the winding of the relay 58, thence over the sleeve of plug 3 and jack 4 and the winding of the relay 62 to ground through the contacts 96 of this relay, and a resistance unit 94. The response of the relay 62 connects grounded battery over its contacts 33 through the winding of the relay 22 to ground. The response of relay 22 disconnects the sources of alternating currents 20 and 21 and establishes leads presently to be joined with the toll line L, to the main conductors of the jack 90. Closure of the contacts 28 of the relay 22 closes a circuit traceable over the contacts 59 of the relay 62, whereby at the instant the pull of the relay 62 will have disconnected the ground through these contacts, battery current from the sleeve connection may continue through the contacts 28 of relay 22 and the winding of the relay 10 to ground. The response of the latter relay switches the line circuit L from the equipment E and connects the line by way of the upper alternate contacts of the relay 22 to the jack 90. Since the relay 10 may respond following the response of the relay 22 only, it will be clear that in taking up the line circuit at the jack 90 no impulse of alternating currents from the sources 20 and 21 may be applied to the line circuit L at this time. The next lowermost transfer contacts of the relay 22 effect circuit changes on the leads 43, 53 and 63 in establishing a busy condition at the jack 4 and also on other equipment not shown but in duplicate of the equipment shown at T¹ and E², Fig. 2, which will presently be described relative to this busy test feature.

In order to call the distant toll center, the operator may momentarily depress the ringing key 55, thereby applying alternating currents at 700 and 900 cycles per second from the sources 70 and 71 to the toll line. At the distant equipment E² the 900 cycle current may be considered as idly present while the 700 cycle current may effect re-

sponse of the alternating current relay 240 in disconnecting the zero resistance ground normally established in parallel with the ground which may be traced through the local contacts of the 1100 cycle relay 230 and the left-hand winding of the relay 260. Current normally present from grounded battery, through the winding of the relay 250 and the normal contact of the relay 255 may now continue through the contacts of the relay 230 and the winding of the relay 260 in continuing the energized condition of the relay 250 while at the same time effecting response of the relay 260. Current from grounded battery may now be traced from the uppermost normal contacts of the relay 220 through the right-hand normal contacts of the relay 275, thence through the line signal 267 to ground through the right-hand contacts and locking winding of the relay 260. On cessation of the 700 cycle ringing current, although restoring of the relay 240 effects shunting down of the left-hand winding of the relay 260, the latter relay will, however, continue energized by current over the circuit just traced through its right-hand winding. In addition to energizing the line signal 267, the relay 260 also closes a path through its left-hand contacts to apply current present as traced through contacts of the relays 220 and 275 to the conductor 253 to actuate the busy signal 254, and through associated condensers 288, 281 and 282 to establish a busy test condition on the sleeve of the jacks 200, 251 and 299 while the outer right-hand contacts of the relay 260 switch the private terminal 226 of the bank contact group B¹ to ground in establishing a busy condition for these bank contacts.

Assuming that the line signal 267 may be suitably multiplied with other similar signals (not shown) and adapted for association with the jacks 200, 251 and 299, the present call may be taken up at either one of these jacks. However, on the basis that it will be answered at the jack 299, which may be considered as present at an inward operator's position, a plug 261, which may be in association with a cord circuit similar to the cord circuit C Fig. 1, may be inserted in this jack. Current from grounded battery over the sleeve conductor of this cord may then be traced through the left-hand winding of the relay 275 and the lower winding of the relay 220 to ground. The response of the relay 220 switches the toll line circuit from the automatic equipment at the right-hand side in connecting the line L to the main members of the jack 299 which are also joined common to the main segments of the automatic or bank terminals B¹. The uppermost contacts of the relay 220 disconnect the grounded battery from the circuit already traced through the line signal 267 and the relay 260, thereby effect-

ing release of this relay and deenergization of the signal 267. These contacts of the relay 200 also apply battery to energize the busy lead 253 in retaining the signal 254 operated while continuing the condensers effective relative to the click busy test condition on the jacks 200 and 251. The left-hand contacts of the relay 275 which responded in series with the relay 220, switch the circuit of the terminal 223 of the bank contacts from ground potential at relay 260 to ground potential of the left-hand armature of relay 275 thereby continuing the busy condition on the bank contacts as first applied by the relay 260.

The busy test condition just described as present at the equipment T¹ and E² (Fig. 2) corresponds with the busy condition established at the duplicate distant equipment T and E Fig. 1, at the instant the cord circuit C was joined to the jack 90 of the toll line. The jacks 4 and 90 and the relays 22, 10 and 62 at the first end of the line correspond with the jacks 200, and 251 and relays 222, 215 and 235 at the other end of the circuit. Therefore, it is believed that the matter of duplicate equipments at each end of the toll line L may be readily understood from the complete illustration of this equipment at one end of the circuit (Fig. 2) only, in connection with partial illustration of the equipment at the other end of the line, thereby avoiding repetition or duplication in the drawings.

From the descriptions already given, it will be obvious that in establishing a connection between two remote subscriber stations over the toll line L on the present assumed manual basis under which this line is now held by the outward operator and the inward operator at the respective toll centers, the originating operator may insert the plug 2 of the cord circuit C into the jack of a toll switching trunk of either automatic type, manual common battery type or manual ring-down type, in reaching the line of a calling party, while the inward operator may similarly employ the corresponding plug of a like cord circuit in extending the connection over either one of the several types of toll switching trunks mentioned in order to reach the line of a station which may be wanted. For the respective local ends of the present assumed connection, the supervisory signal 87 may serve as already described as an indicator under control of the subscriber station locally connected over the plug 2, while respective ringing keys 55, alternating current relays 80 and 81 with associated devices may serve for the control of either supervisory signals or for clearing-out signals between the remote operators' positions.

Under ring-down control the signal 75 is arranged automatically to be conditioned so

that it respectively be energized or deenergized in such a manner that the indications will be substantially the same as indications had with the supervisory control on automatically completed connections similar to the connection already described. Supervision of this kind corresponds to so-called positive supervision as usually employed on cord circuits used in connection with common battery lines, and is characterized by an energized condition of the signal prior to response at the station on a line connected and deenergization of the signal during periods the instrument at a station may be in the talking position. In order to accomplish these features the marginal relay 58 of the cord circuit C will not receive sufficient current to effect its operation when the plug 3 is present in the jack 90. This is due to the higher resistance of the sleeve conductor path from this jack as first completed through the winding of the relay 62 and the resistance unit 94, and also during and after substitution of the winding of the relay 19 for the resistance 94 in series with the relay 62. No effect results immediately from the inert position of the relay 58 following insertion of the plug 3 into the jack 90 therefore the signal 75 will be displayed in the same manner as when this plug may be joined to the jack 4 as already described. On the ringing key 55 being operated, however in order to display the distant line signal 267, the battery control contacts of this key disconnect grounded battery as now present through the lowermost normal contacts of the talking key 19 and the left-hand normal contacts of the relay 58, to the armature of the polarized relay 9, and apply this battery by way of the right-hand normal contacts of the relay 58 through the winding 8 of the relay 9, thereby shunting down the winding of the relay 7 as supplied with current from grounded battery through the contacts of the relay 6. This results in the armature of the relay 9 being moved to its upper bias while the relay 7 will restore to disconnect the signal 75 and to apply grounded battery to the sleeve of the connection by way of the winding of the relay 6 and the lower coil 13 of the relay 9.

The signal 75 may continue deenergized during the period of the connection. In case one of the operators may desire the attention of the other operator the respective ringing key 55 may be successively operated as in a flashing operation, thereby effecting corresponding application of the 700 and 900-cycle ringing currents to energize the respective distant alternating current relays 80 and 81. From the previous description it will be obvious that the signal 75 will be caused to flash in the cyclic order that arrival of a first impulse of ringing currents the relays 80 and 81 will cause the signal 75

to be energized while a second impulse of the ringing currents will cause the signal 75 to be deenergized. Operation of the associated talking key 19 in responding to this 5 signal may at the normal battery control contacts of this key, disconnect the current supply as routed by way of the left-hand normal contacts of the relay 58, the lowermost normal contacts of the ringing key 55 and 10 the normal contacts of the relays 80 and 81 to the armature of the relay 9, while at the alternate battery contacts of the key 19 the grounded battery will be applied over the right-hand normal contacts of the relay 15 58 through the upper winding 8 of the relay 9 to the sleeve conductor of the connection. This results in the armature of the relay 9 being moved to its upper contact stop 68, and the shunting down of the relay 7 which 20 will then release and extinguish the signal 75.

From the foregoing description it will be obvious that operation of either the ringing key 55 or the talking key 19 will result in the disabling of the supervisory signal 25 75. Therefore, this signal will be conditioned for the reception of either a flashing signal or a steady signal to respectively indicate that a connection requires attention or that it may be taken down. To give a 30 disconnect signal one operator, usually the originating operator, gives such a signal to the distant inward operator by a single application of the ringing currents to the line by means of the respective ringing key 55, 35 thereby causing the distant signal 75 to be energized steadily. In response to such a signal the inward operator may take down the connection at that point, thereby permitting all devices to restore to their normal positions, while removal of the cord at the outward position permits similar restoring of 40 the equipment at that point, following which the circuit may be taken for use at any one of the several points respectively present for 45 such purpose at each end of the line circuit.

In describing operations in connection with the employment of the cord circuit C on toll lines or trunk circuits of the ring-down type, let it be assumed that the plug 2 50 may be inserted in the jack of such a circuit (not shown). The low resistance of the ground connection from the sleeve of such a toll line or trunk line jack permits current 55 of sufficient strength through the marginal relay 35 to effect its operation, therefore, on reception of ringing current at low frequency (16 or 20 cycles per second) such current may complete circuit through the 60 bridge path formed by the serially connected windings of the alternating current relays 80 and 81 and the right-hand winding of the relay 77. Response of the relay 77 to this 65 ringing current results in establishing a self-locking circuit for this relay which may be

traced from grounded battery, through the contacts 85 of the talking key 19, signal 87 the alternate contacts of the relay 35 and the left-hand winding of the relay 77 to ground through the contacts of this relay. The signal 70 87 accordingly will be displayed until, in response to this call, the key 19 may be moved to the talking position, thereby opening the circuit through the left-hand winding of the relay 77 to permit this relay to 75 restore and deenergize the signal. During energization of the signal 87 as just described the limiting of current strength therethrough is effected by the left-hand winding of the relay 77 the resistance of 80 which is the same as that of the resistance unit 29, present in series with this signal on connections where the marginal relay 35 may not respond as already described.

In order that connections may be extended 85 through automatic or machine switching equipment to the toll line L as may be desired from tributary offices or switching points adjacent to the toll centers proper, between which the toll line L is assumed to 90 extend, trunk circuits from such tributary points may terminate in automatic switches at the toll centers, respectively. Under the control of an operator at a tributary point the switching devices may be advanced to 95 engage the bank terminals B¹ (E² Fig. 2). Ground potential present on the private wiper of such a switch (not shown) may complete circuit over the contact 226, the outer right-hand normal contacts of the relay 260 left-hand normal contacts of relay 275 and thence to grounded battery through the upper winding of the relay 220. The response of the latter relay switches the conductors of the toll line from the inward equipment at the right-hand side to the main conductor segments of the bank contacts B¹. The uppermost alternate contacts 100 of the relay 220 apply battery to the busy conductor 253 to energize the busy signal 105 254 and to place busy test potential through respective condensers to the sleeve points of the jacks 200, 251 and 299. Assuming that equipment, similar to the equipment of the cord circuit C present at the originating operator's position, may be at the assumed 110 tributary point, a connection may be completed and handled over the toll line L on a manual or ring-down basis in a manner similar to that already described by means of 115 the cord circuit C.

Referring to the arrangement whereby the right-hand contacts of the relay 418 may effect momentary response of the relay 425 120 at the instant the former relay may release due to cessation of a first series of impulses received at the selector K, it will be pointed out that in situations where it may be considered desirable the lead 468, instead of being connected via switch 467 to control the 125 130

heavy duty relay 425, may be joined via the two lower contacts associated with switch 467 in derived circuit relation to the conductor extending from the left-hand winding 5 of the relay 416 whereby grounded battery is supplied to the trunk circuit L^2 . This connection provides that during release of the relay 418 its right-hand contacts will momentarily apply ground potential present 10 at such times by way of the lowermost alternate contacts of the off normal switch 455 to shunt down the battery supply circuit, thus effecting cessation of current in the loop of the trunk L^2 . This effect will be similar 15 to that already described, for control of the circuit L^2 through the interrupter 488. Following this, the relay 372 at the repeater TS may momentarily respond in controlling effects already described for applying an impulse 20 of alternating currents to the toll line L .

At the repeater TS a similar arrangement may be substituted for the one shown, whereby the left-hand contacts of the relay 372 effect momentary responses of the relay 352. To accomplish this, the lead 363 may be transferred from junction with the conductor leading from the winding of the relay 352 via the two right-hand contacts associated 30 with switch 369 to the lead extending from the left-hand winding of the relay 350 employed in supplying battery to the loop of the trunk circuit L^1 . Under this arrangement and during periods the relay 356 may be inert, responses of the relay 372 may apply full potential ground present through the contacts 366 of the relay 356 to momentarily shunt down the battery supply to the trunk circuit L^1 . Thereupon the relay 280 35 may respond to control the relay 225 in sending an impulse of alternating currents over the toll line as above described.

In connection with control of the relay 280 by current changes in the trunk circuit L^1 , 40 attention will be directed to effects set up by and characteristic of the operation of current reversing relays in automatic switches of the present type. Referring to the relay 352 it may be noted that two sets 45 of make-before-break contact spring groups comprising three members each are required for the purpose of reversing the polarity of the current supplied through the two windings of the relay 350 to the main conductors 50 which may be joined to the trunk circuit L^1 under the conditions of a connection. In effecting a polarity change relative to this current supply, no cessation of current 55 should take place whereby the relay 350 may be permitted to deenergize. Therefore, the interconnections between the six-contact members as shown in the drawing, are in the relation that during movement of the armature of the relay in either direction an 60 interval or period of time will be present 65

during which the entire six contact members will be in actual contact or common one with the others. This joinder of all the contacts results in non-cessation of current in the relay 350. On the opposite or trunk-loop side 70 of the relay 352, however, entire cessation of current will take place since a zero resistance path or short-circuit will be present through the commonly joined six contact members at the instant they form a passing 75 juncture. It necessarily is a characteristic of reversing relays of this type that the contact members be so arranged that a decidedly definite follow effect be present to insure that the contacts never may fail to effect common 80 juncture, therefore, this shunting effect will always be present for an appreciable interval of time. To illustrate the utilization of this effect in the present system, let it now be assumed that the circuits may be in the condition already described under which the relay 280 will be joined across the trunk circuit L^1 while this trunk may be joined to the repeater TS, where the relay 352 may be assumed as in its normal position as shown, 85 in establishing a current condition of positive polarity in the lowermost conductor and negative polarity in the uppermost conductor of the trunk L^1 . The relay 280 therefore may be considered as energized in 90 a first magnetic sense. Assuming that the relay 352 may now be caused to respond, the described moment of no current in the trunk circuit effected by the passing or common engagement interval of the contact members of 95 this relay permits deenergization of the relay 280. At the instant the contact members of the relay 352 may have reached their separating point, current will build up in the opposite polarity relation in the trunk 100 circuit and the relay 280 accordingly will respond to energy setting up an opposite 105 magnetic sense. The energy or wattage component for the operating circuit of the relay 225 is relatively high, while the capacity of the condenser 244 bridged on this relay is so proportioned that while capable of imparting sufficient lag in the release of this relay to render it capable of but a single 110 response under a condition corresponding with two applications of current by the relay 280 as influenced by a current reversal as just described, the time constant or speed of response and release of the relay 225 permits it, however, to operate substantially in 115 unison with flashing operations which may be set up by the various interrupters associated with the automatic switches for this purpose, and also to flashing operations at a connected station, as already described in the 120 assumed connection to the station B.

It will be further pointed out that the time constant of operation of the relay 280 is such that under a reversal of current polarity through its winding its armature will 125 130

respond to the collapsed or dying out of the magnetism of the first sense before the time that the magnetism may build up in the opposite sense. The time of such changes it will be understood, may substantially be considered as within the usual rate or speed of operation of the switching devices employed in systems of the present nature. From the foregoing it will be obvious that although the armature of the relay 280 may execute a complete to and fro movement, and thereby establish two impulses of current through the winding of the relay 225, in response to a single reversal of current in the trunk circuit L, as may originate from a single movement of the switchhook at an inwardly connected station, one response only will be had from the relay 225 in effecting a single application of alternating currents to the toll line L.

Referring to features of the busy test and busy signal arrangement it may readily be understood from the description already given that the conductor 253 (Fig. 2) connected as a common means for energizing the busy signal 254 and the test members of the jacks 200, 251 and 299 may receive current either by way of the relay 260, the switching relay 220 or the busy relay proper 275, while the bank contacts 226 may be rendered busy either by the relay 260 or the relay 275. As indicated in the drawing, the relays 220 and 275 are of quick-to-operate but slow-to-release type. The latter feature for the relay 275 insures that following release of a connection handle more particularly on an automatic basis over the toll line L, the busy condition may continue at the outward end of the circuit until the devices at the opposite or inward end will have restored to their normal position. This feature further provides that the clearing of busy condition may take place at substantially the same instant at each end of the toll line circuit. The feature of simultaneous clearing of a busy condition at each end of the line circuit is also had for calls handled on a manual or on a ringdown basis. The slow-to-release feature of the relay 220 insures that this condition will obtain for connections which may be established by way of the automatic or bank contacts B¹ relative to an outward or originating call. Under disconnect, the relay 222 switches the busy relay 275 to the grounded release lead 263, subsequently disconnected by release of the relay 310 at the selector S. Relative to the switching of the main conductors of a connection, inspection of the drawing (Fig. 2) will render it obvious that a connection by way of the jack 200 or the jack 251 will result in disconnection or clearing of the toll line L by means of the relay 215 from all equipment and devices E² relative to inward or outward service except

that the two jacks mentioned to which the toll line will then be joined by means of this relay 215. In turn, during the presence of connections by way of either the jack 299 or the bank contacts B¹ the equipment T¹ will be clear of the toll line due to inert condition of the relay 215 while all inward equipment at the right will be cleared or disconnected and the toll line will be joined to the bank contacts B¹ and the jack 299 by means of the relay 220. This handling of the main conductors of the line circuit relative to elimination of all equipment not necessary to any given connection, while reducing the possibility of irregularities in the functioning of the different respective groups of devices, also avoids transmission losses as otherwise would result through such devices as may be extraneous to any given connection.

In further reference to features of the equipment T, attention will be directed to the duplicate equipment at T¹ (Fig. 2) where the arrangement is shown complete with associated equipment E². The resistance of the winding of the relay 215 may be relatively high, therefore, on a cord similar to the cord circuit C being joined to the jack 200 the greater portion of the energy or wattage available over the sleeve strand of the cord will be absorbed or utilized by this relay. The resulting quick response of this relay therefore effects immediate connection of the associated alternating current sources to the line L. The circuit of the relay 222 is normally open and may be closed only by full response of the relay 215 at which instant the parallel relation of the winding of this relay with the relay 222 while reducing the energy available on the instant for energization of the relay 222 nevertheless permits a sufficient increase in current to effect or to insure response of the marginal relay 58 present in the sleeve path of the cord circuit. Following equalization of energy or the arrival of the moment when a steady current condition will be present in the various coils in this sleeve circuit, the necessary energy will slowly build up in the relay 222 and gradually offset the lagging effects present in this relay following which it may respond and disconnect the sources of alternating currents. The adjustment of the relay 222 may be such that the slowly building up effects of current supplied from the sleeve path of the cord circuit may result in closure of the contacts 207 in advance of the separation of the contacts 206. Closure of the contacts 207 connects direct current by way of the resistance unit 227 in parallel with the current supplied through the devices of the cord circuit, and due to this augmentation of current through the relay 222 its armatures may be moved to such a point as will result

in separation of the contacts 206, following which the current supplied through the resistance 227 only, may be present to slowly advance the armature to the point where disconnection of the alternating currents will take place just before final seating of the armature in closing the circuit of the toll line to the jack 200. The adjustment of the relay 222 further provides that the outer right-hand grounding contacts may close in advance of closure of any other of the contacts on this relay.

The described sequence or order of response of the relays 222 and 215 at the instant a cord circuit may be joined to the jack 200, and the resulting application of an impulse of alternating currents of predetermined length to the line L, is as has already been described, for the purpose of causing a slow-to-release relay, as the relay 250, at the distant or opposite end of the line circuit to restore and thereby initiate operations to condition equipment at that point for the reception of impulses of alternating currents of a switching or selective nature. The inverse effect whereby the relays 222 and 215 may apply an impulse of alternating currents from the same current sources and substantially of the same time interval or duration to the line L at the instant the assumed cord may be removed from the jack 200 results from features more particularly characteristic of the interconnective and switching relation previously brought into play and above described in connection with the first impulse of current sent to the line circuit. During the continuation of a connection the relay 222 is retained in series with the battery supply over the sleeve strand of the cord circuit while the relay 215 is retained due to the battery supplied in series with the resistance unit 227. Therefore, removal of the cord from the jack 200 results directly in deenergization of the relay 222. The immediate restoring of this quick-to-release relay results in its right-hand inner and intermediate armatures first switching the toll line to the alternating current sources 228 and 238 following which, the contact sets 206 and 207 form a momentary or passing junction which places the relatively low resistance winding of the relay 222 in parallel with the higher resistance winding of the relay 215. Although this effects an appreciable hesitation in the releasing movement of the relay 222, the relatively high resistance value of the unit 227 prevents retaining of the relay 222 which accordingly may continue to its fully released position. This period of hesitation or additional lag for the relay 222 prolongs the period during which the slow-to-release relay 215 may continue to receive energy. The relay 215 is characterized by low strength of retaining

or holding current therefore this relay will not release due to the momentary parallel relation of the relay 222. It will thus be seen that relay 215 does not become deenergized until relay 222 is fully restored to normal and that since relay 215 is of the slow-to-release type that a short interval will ensue during which alternating current from the sources 228 and 238 will be connected to the toll line.

Referring to the features of the present system relative to the employment of alternating currents at a plurality of different frequencies to form individual impulse intervals and to the arrangement for reception of such selective or signaling currents by means of a plurality of receiving devices respectively tuned for such frequencies, it will be pointed out that in addition to employment of the present system on ordinary telephone circuits it is particularly adapted for use on phantom circuits, phantomed physical circuits, on all forms of telephone circuits equipped for any arrangement of superposed telegraph working and on circuits equipped with telephone repeaters. Substantially all telephone circuits not in the class of ordinary physical lines possess characteristics that preclude the employment of signaling currents at low frequencies. One reason for this is that the devices required on such circuits cause excessive transmission losses for such currents, while another reason is that currents at low frequency set up interference effects relative to the telegraph channels. On substantially all such circuits particularly those equipped with telephone repeaters or with the more modern superposed telegraphic arrangements, a further limitation or requirement is restriction of amplitude or strength permissible for such signaling currents. In general the strength of these currents may not exceed the amplitude of voice currents possible for suitable transmission or conversation. In order to meet such limitations and requirements it will be obvious that alternating currents within the so-called voice range of frequencies must be resorted to particularly for the purpose of meeting the conditions relative to efficient transmission, while receiving devices substantially of supersensitive type will be necessary in order to meet the requirement relative to low current strengths. Therefore, it will be clear that the receiving devices employed necessarily must be characterized by sensitivity to a degree which render them susceptible of response when subjected to voice currents. Relative to effecting response of such devices, currents from a single voice may at any given instant, set up currents at one frequency only. Therefore, inflections, modulations or changes of pitch of a voice in speaking, although capable of covering a

wide range of frequencies relative to telephone currents or transmission, may at any particular instant produce but one dominant pitch or resulting frequency of alternating currents. It will therefore be readily understood that when a plurality of alternating current receiving devices respectively tuned for different frequencies may be arranged in such a manner that translation of a signal therethrough may take place at such times only as will correspond with the simultaneous reception of a corresponding plurality of alternating currents at similar different frequencies to effect response of each of the receiving devices, translation of signals will not result from the presence of voice currents in such receiving devices, which may be joined to the main conductors of a telephone circuit during talking periods. The foregoing characteristics form the basis relative to the employment of the supervisory control relays 80 and 81 common to the main strands of the cord circuit C, and also the relays 230 and 240 connected on the main conductors at the equipment of Fig. 2 during periods the circuits may be in the talking position. At the cord circuit C, assuming at a given instant, that voice currents at 700 cycles per second may be present, resulting response of the 700 cycle relay 80 will be ineffective due to the fact that the 900 cycle relay 81 will be inert at such time during which its local contacts joined in parallel with the local contacts of the relay 80 will maintain any previously existing condition of the circuits of the signal 75. In an inverse manner, during any instant the 900 cycle relay 81 may be under energization due to voice currents, the 700 cycle relay 80 will be inert and therefore prevent any circuit changes relative to the supervisory signal 75. The parallel relation of the local contacts of the relays 230 and 240 render these relays capable of retaining a connection under similar voice current effects relative to individual response of either one or the other of these relays at any given instant, in a manner similar to that just described in connection with the relays 80 and 81.

While two relays have ordinarily been found to constitute a sufficient guard against interference from the effect of voice currents as described, it will be pointed out that additional relays tuned to respond to respectively different frequencies may be included with the two relays shown in the drawing. Such an arrangement is shown in Fig. 2^B where three serially connected relays 230^B, 240^B and 241^B indicated as being tuned to respond to currents at 1100, 700 and 900 cycles per second, respectively, are serially connected to form a bridge path across the main conductors of a circuit. The local contacts of these relays have been connected in paral-

lel one set of contacts with the others in such a manner that the relays may be substituted for the relays 230 and 240 relative to control of the associated inward equipment. In such an arrangement it will be obvious that three sources of current at corresponding frequencies would be required at the relays 42 and 22 (Fig. 1) and relay 222 (Fig. 2) with respect to the sending of impulses. Assuming the presence of such an impulse of current in the three relays, 240^B, 230^B and 241^B the circuit of the relay 250 will be disconnected to effect release of this relay in the same manner as that already described. Under manual or ringdown operation the reception of current at 700 and 900 cycles per second as may be applied by the ringing key 55 of the cord circuit C, results in response of the relays 240^B and 241^B to remove the shunt path normally present on the left-hand winding of the line relay 260^B, therefore, battery current may continue through the local contacts of the 1100 cycle relay 230^B to ground by way of the left-hand winding of the relay 260^B. Response of the latter relay will effect energization of the line signal 267^B in the same manner as that already described for the equipment of Fig. 2.

The presence of the third relay 241^B renders it possible for tone currents set up simultaneously by two different voices to respectively become effective with two of the relays without resulting in translation of a signal due to the fact that the signaling or selective circuits may continue retained by the inert position of the third relay at such times.

Relative to control of the line signal 267^B, no voice currents may be present on the circuits during periods the equipment may be at rest or in position for the reception of such a call. At all other times the left-hand or operating winding of the relay 260^B will be disabled either by being shunted down at the left-hand forward contacts of the relay 275 or by being disconnected from the grounded battery at the normal contacts of the relay 250, as brought out in the description already given.

From the above description in connection with the three relay arrangement of Fig. 2^B it will be obvious that if desired a corresponding number of relays may be employed at the cord circuit C, for the supervisory control operations at present under control of the relays 80 and 81.

It may be mentioned that the presence at one and the same time of currents from the tones of two different voices would not ordinarily be a service condition, and further, if present it is not likely ever that at any given moment the frequencies of such dual currents would bear the relation one to the other that response of two alternating cur-

rent relays would result. Under known or ordinary conditions it is considered, therefore, that the combination of the two alternating current relays as shown in the drawings will be adequate.

With further regard to the employment of two frequencies 700 and 900 cycles per second for ringing operations as may be controlled by the key on the cord circuit C, the alternating current relays 484 and 485 at the connector K will be present on the main conductors during the reception of the last two trains or series of selective impulses required in controlling this connector. The fact that the selective impulses are formed of currents at 700 and 1100 cycles per second render it obvious that the 700 cycle current of such impulses may become effective in the relay 484. During such periods, however, the inert position of the 900 cycle relay 485 serves to retain the circuits already described as controlled by these alternating current relays. The relays 484 and 485 are so connected by way of the uppermost normal contacts of the relay 425, that they will be removed from across the main leads by being short-circuited, owing to the operated position of this back bridge relay 425 during talking periods.

Ringing current applied by means of the key 55 to operate the distant relays 484 and 485 also may effect operation of the 700 cycle relay 240 (Fig. 2). At such times, however, the inert position of the associated 1100 cycle relay 230 will prevent interruption of the circuit of the relay 270, present in the circuit at such times.

The features relative to employment of the two frequencies for signaling under manual or ringdown control of a connection are believed to have been sufficiently described already, and therefore will not be referred to further.

Although the various groups of alternating current relays of this system have been shown connected in series, one relay with the other, it will be understood that the relays may be connected in any other relation as may be desired, and further, in addition to being mechanically tuned to the respective frequencies electrical tuning may be added or employed in substitution for the mechanical tuning already referred to for these relays.

An alternate arrangement will now be described whereby selectors and connectors of unmodified type relative to the use of alternating currents for returning signals from such points may be employed. Under strict traffic procedure where it may be assured that the dialing key 44 may remain in its operated position until dialing operations have been entirely completed and either the busy signal or the signal to indicate that a connection has been completed

to the line of the distant station desired has been received on the dialing signal 41, the alternating current relay 40 may be of universal type relative to being capable of responding to currents through a wide range of frequencies, therefore alternating currents constituting the usual dialing tone and busy tone signals may be relied upon for operation of the relay 40 in controlling the signal 41. At the selector switches S, S² and at the connector K such currents may be supplied in the conventional manner in which currents of this nature are employed in connection with switches and connectors of the present types when arranged for the handling of local service only.

The frequency of such tone currents is usually near the lower limits of the voice range of frequencies, and therefore, the universal range of frequencies for the relay 40 may be sufficient when extended to include the frequencies commonly employed for dialing and busy tone indications, and the frequencies controlled by the relay 225 (700 and 900 cycles in the present disclosure). The latter currents are employed for controlling the signal 41 at the instant the first selector S may seize the repeater TS, and also when the selector S² may seize the connector K, and also for supervisory control as already described.

Under this arrangement no special tone frequencies would be met by subscribers or operators who also may have access to the switches and connectors of this system, for use in completing connections therethrough on a non-toll or local service basis.

Relative to definite indication of frequencies for the various alternating currents employed in the present system, such choosing of frequencies as indicated in the drawings and referred to in these descriptions have been made entirely from the standpoint of convenience of description. Therefore it will be understood that any desired frequencies or combinations thereof may be employed in the operation of this system, as may be best adapted for the line circuits and the devices controlled either in any particular situation or in the establishing of a general standard of frequencies, without departing from the spirit of this invention.

What is claimed is:

1. In a telephone exchange system, a called station, means for supplying alternating current impulses, a plurality of vibratory relays directly energized by said alternating current impulses, means controlled by said relays for establishing a connection with said called station, and means for giving supervision back from the called station.

2. In a telephone exchange system, a first office, a second office, a trunk line extending

- between said offices, a calling station at the first office, a called station at the second office, means for supplying alternating current impulses, a plurality of vibratory relays directly energized by said alternating current impulses for establishing a connection over the trunk line between the calling and called stations, and means for giving supervision back over the trunk line.
10. 3. In a telephone exchange system, a first office, a second office, an operator's position at the first office, a called station at the second office, means including automatic switching mechanism for connecting the called station with the operator's position, means for supplying alternating current impulses, a plurality of vibrating relays directly energized by said alternating current impulses for actuating said automatic switching mechanism, and means for giving full supervision to the operator.
4. In a telephone exchange system, a first office, a second office, a trunk line extending between the offices, an operator's cord circuit at the first office, an automatic switch at the second office, means for sending an alternating current impulse over the trunk, means for sending alternating current impulses over the cord and connected trunk, and means including a plurality of vibratory relays directly energized by said first mentioned impulse to extend the trunk line to said switch and by said second mentioned impulses for setting said switch.
35. 5. In a telephone exchange system, a first office, a second office, a trunk line for interconnecting said offices, an operator's cord circuit at the first office, an automatic switch at the second office, sources of alternating current, means responsive to the connection of the cord with the trunk circuit for applying current from said sources to said trunk, means for interruptedly applying current from said sources to said cord and said connected trunk, and means including a plurality of vibratory relays directly energized by current from said first applied sources to extend said trunk line to said switch and by said interrupted current for setting said switch.
6. In a telephone exchange system, a first office, a second office, a trunk line extending between said offices, automatic switches at the second office, sources of alternating current, an impulse sender at the first office for applying current from said sources to said trunk line, means including a plurality of vibratory relays directly energized by alternating current impulses from said sender for setting said switches, and translating means responsive to alternating current to indicate when the switches are ready for receiving impulses.
7. In a telephone exchange system, a first office, a second office, a called station at the second office, means including an operator's cord circuit, a trunk line and an automatic switch for extending a call from the first office to the called station, sources of alternating current, a switching device controlled by the operator for applying alternating current to the trunk line for initiating the movement of said switch, an impulse sender for interruptedly applying alternating current from said sources to said trunk, means including a plurality of vibratory relays directly energized by alternating impulses from said sender for setting said switch, a supervisory signal in said cord circuit, and means for actuating said signal to enable the operator to supervise the connection.
8. In a telephone exchange system, a first office, a second office, a called station at the second office, means including an operator's cord circuit, a trunk line and an automatic switch for extending a call from the first office to the called station, sources of alternating current, an operator controlled switch for applying current from said sources to the trunk line, an impulse sender for intermittently applying current from said sources to the cord circuit, and means including a plurality of vibratory relays directly energized by the current applied by the operator controlled switch to extend the talking conductors of the trunk circuit to the automatic switch and by the current applied by the sender to set the switch on the called line.
9. In a telephone exchange system, a first office, a second office, an operator's cord circuit at the first office, a called station at the second office, means including a trunk line and an automatic switch for extending a connection from the operator's position to the called line, sources of alternating current, an operator controlled switch for applying current from said sources to the trunk line, an impulse sender for sending alternating current impulses over said cord and trunk circuits, means including a plurality of vibratory relays directly actuated by the current applied by the operator controlled switch to extend the trunk circuit to the automatic switch and thereafter by the sender to set the switch on the called line, and translating means responsive to alternating current to indicate to the operator when the sender may be actuated.
10. In a telephone exchange system, the combination with telephone lines, groups of trunks, automatic switches adapted to connect said lines over said trunks, means effective when the switches are ready for dialing for giving a signal of one character, means controlled by the busy condition of a selected trunk group for giving a signal of

another character, and means controlled by the busy condition of the selected line for giving a signal of still another character.

11. In a telephone exchange system, the combination with telephone lines, automatic switches, groups of trunks terminating therein, an operator's position, a signal thereat, means controlled from said position for setting said switches to interconnect said lines over said trunks, means effective when the switches are ready for setting for operating said signal in one manner, means controlled by the busy condition of a selected trunk group for operating said signal in a different manner, and means controlled by the busy condition of the selected line for operating said signal in a still different manner.

12. In a telephone exchange system, the combination with telephone lines, automatic switches, groups of trunk lines terminating therein, an operator's position, a lamp thereat, means controlled from said position for setting said switches to interconnect said lines over said trunks, means operative when the switches are ready for setting for lighting said lamp steadily, means controlled by the busy condition of the selected line for flashing said lamp in one manner, and means controlled by the busy condition of a selected trunk group for flashing said lamp in another manner.

13. In a telephone exchange system, the combination with an automatic office including automatic switches, subscribers' lines terminating therein, a toll operator's position including an operator's telephone circuit having a supervisory lamp therein, a dial associated therewith, means actuated when the switches are ready for dialing for lighting said lamp steadily, means actuated in case one of said switches fails to find an idle trunk for flashing said signal in a certain manner, and means actuated in case the connector finds the selected line busy for flashing said lamp in a different manner.

14. In a telephone exchange system, a first office, a second office, a trunk line extending between said offices, a manual connecting terminal and an automatic switch accessible to said trunk line at the second office, sources of alternating current at the first office, and means including a plurality of vibratory relays at the second office selectively and directly energized by current from said sources for extending the trunk line to the manual connecting terminal or the automatic switch.

15. In a telephone exchange system, a first office, a second office, a trunk line extending between said offices, a manual connecting terminal and an automatic switch accessible to the said trunk line at the second office, sources of alternating current at the first office, means for variably applying current from said sources to said trunk line, and

means at the second office including a plurality of vibratory relays directly energized when certain of said sources are applied to the trunk line for extending said line to said manual connecting terminal and when certain other of said sources are applied to said trunk line for extending said line to said automatic switch.

16. In a telephone exchange system, an operator's position, a called station, means including an automatic switching mechanism for connecting the called station with the operator's position, means for supplying alternating current impulses, electromagnetic means energized by said alternating current impulses for actuating said automatic switching mechanism, and means for informing the operator of the progress of the connection.

17. In a telephone exchange system, an operator's position, a called station, means including an automatic switching mechanism for connecting the called station with the operator's position, means for supplying alternating current impulses, electromagnetic means energized by said alternating current impulses for actuating said automatic switching mechanism, and visual and audible means for informing the operator of the progress of the connection.

18. In a telephone exchange system, an operator's position, a called station, means including an automatic switching mechanism for connecting the called station with the operator's position, a supervisory signal, means for supplying alternating current impulses, means including a plurality of vibratory relays directly energized by said alternating current impulses for actuating said automatic switching mechanism, and means responsive to the closure of the called line for actuating said supervisory signal to inform the operator that the subscriber at the called station has answered.

19. In a telephone exchange system, an operator's position, a called station, means including an automatic switching mechanism for connecting the called station with the operator's position, a supervisory signal, means for supplying alternating current impulses, means including a plurality of vibratory relays directly energized by said alternating current impulses for actuating said automatic switching mechanism, and means responsive to the closure and opening of the called line for successively actuating said supervisory signal.

20. In a telephone exchange system, a transmission line, a cord circuit, a visual signalling device associated therewith, a plurality of automatic switches, a sender for setting said switches, and means automatically operated after each switch has been set for actuating said signal.

21. In a telephone system, a transmission

- line, a cord circuit, a visual signaling device associated therewith, automatic switches including a switch having a plurality of directly controlled movements, a sender for 5 setting said switches, means automatically operated after each directly controlled movement of said switches for actuating said signal, and means for disabling said sender until said signal is actuated.
- 10 22. In a telephone system, a transmission line, a cord circuit, a visual signaling device associated therewith, automatic switches including a switch having a plurality of directly controlled movements, a sender for 15 setting said switches, means for disabling said sender after said sender has been actuated, and means for actuating said signal after the directly controlled movements of said switch have been completed and for 20 rendering said sender operative.
23. In a telephone system, a trunk line, operator's equipment including a manual connective terminal at each end of said trunk line, means including said equipment 25 and said switch for completing a connection over said trunk line in either direction, means for supplying alternating current impulses, and means including a plurality of vibratory relays directly controlled by said 30 alternating current impulses for giving full supervision to the operator over an established connection.
24. In a telephone system, a trunk line,
- operator's equipment including a manual connective terminal at each end of said 35 trunk line, means including said equipment and said switch for completing a connection over said trunk line in either direction, means for supplying alternating current impulses, and means including a plurality of vibratory relays directly controlled by said 40 alternating current impulses for informing the operator when the called party hangs up and when the called party flashes.
25. In a telephone system, a two-way 45 trunk line provided with a manual connective terminal at each end, means including one of said terminals and an automatic switch at the other end of said trunk line for completing a connection over said trunk 50 line in one direction, means including the other of said terminals and an automatic switch at the other end of said trunk line for completing connections over said trunk line in the opposite direction, means for 55 supplying alternating current impulses, and means including a plurality of vibratory relays directly controlled by said alternating current impulses for setting said switches and for giving full supervision of 60 the connection.

In witness whereof, I hereunto subscribe my name this 1st day of September, A. D. 1922.

HENRY W. O'NEILL.
